UNITED STATES PATENT OFFICE

VALENTINE J. MOHLER, OF WHEATON, ILLINOIS, ASSIGNOR TO THE LIQUID CARBONIC CORPORATION, OF CHICAGO, ILLINOIS, A CORPORATION OF DELAWARE

BOTTLE FILLING AND CROWNING MACHINE

Application filed March 16, 1928. Serial No. 262,105.

My invention relates to a machine for filling bottles with beverages of the well known type consisting of highly charged water and flavoring matter, and capping the same. In 5 the machine which constitutes the subject matter of this application the bottles are first presented to a syruper by which a definite predetermined amount of syrup is charged into each bottle, and then to a filling and capping head in which the bottle is filled to the desired level and a cap or crown applied thereto, no opportunity being given between the entrance of the charged water and the completion of the crowning operation for the 10 escape of the gas from the liquid.

A machine embodying my invention and in connection with which I have hereinafter described it comprises a rotating bottle carrier having an annular series of pockets or seats 20 in which the bottles may be successively placed by hand or otherwise, a syruper for measuring charges of syrup and discharging them into the bottles as they successively come beneath the syruper and a filling 25 and crowning head beneath which the bottles are successively fed after leaving the syruper and which discharges into each bottle a sufficient amount of carbonated water to fill the bottle to the desired level and then crowns 30 the bottle. The bottle carrier is given a step by step rotation with a pause after each movement of sufficient duration to permit the bottle beneath the syruper to receive its charge and a bottle under the filling and 35 crowning head to be filled and capped, and the filling and crowning head and associated mechanisms are operated by a rotary cam cylinder likewise operated intermittently by the motor which turns the bottle carrier. In 40 my improved machine a clutch is interposed between the constantly driven motor and the machine and the descent of the filling head and associated parts to operative position on a bottle opens the clutch and stops the machine during the filling operation and the 45 restoration of the connection between the motor and mechanisms operated thereby is effected and controlled by the pressure of the air driven out from the bottle being 50 filled by the incoming liquid so that there

is no chance for the machine to resume its movements until the filling is completed and yet no time is lost between filling operations, irrespective of the capacity of the bottles being filled. My invention relates in 55 part to the machine so controlled and to various features of the construction by which such control is effected, to certain improvements in the filling and crowning head and associated mechanisms, and to other features hereinafter pointed out in the claims. It is to be understood, however, that the 60 specific disclosure is for the purpose of exemplification only and that it is the intention to claim the invention and every feature 65 thereof as broadly as the prior art will permit.

In the drawings accompanying and forming a part of the specification:

Fig. 1 is a front view in elevation of 70 the upper portion of the preferred embodiment of my invention;

Fig. 2 is a side elevation of the entire machine viewed from the right in Fig. 1;

Fig. 41 is a side view of a portion of the chute for feeding crowns to the filling and crowning head;

Fig. 42 is a section of the same on the planes of line 42—42 of Fig. 41;

Fig. 43 is a transverse section on the plane of the line 43—43 of Fig. 41;

Fig. 44 is a front elevation of a detail, parts being in section on the line 44—44 of Fig. 45;

Fig. 45 is a vertical section of the same portion of the apparatus on the line 45—45 of Fig. 44, looking in the direction of the arrows;

Fig. 46 is an enlarged vertical section of a detail of Fig. 45, parts being shown in elevation;

Fig. 47 is a transverse section of a detail on plane of the line 47—47 of Fig. 46, looking in the direction of the arrows;

Fig. 48 is a central vertical section through the lower portion of the machine, parts being shown in elevation;

Fig. 49 is a horizontal section on the line 49—49 of Fig. 48;

Fig. 50 is a plan partly in section on the plane of line 50—50 of Fig. 48;

Fig. 51 is a vertical section showing certain details;

Fig. 52 is a similar section with the moving parts in a different position;

Fig. 53 is a plan view of the table of a modified form of machine;

Fig. 54 is a vertical section of the same on the broken line 54—54 of Fig. 53;

Fig. 55 is a horizontal section on the plane of the line 55—55 of Fig. 54;

Fig. 56 is a plan view of the syruping assembly;

Fig. 57 is a vertical section thereof on the plane of the broken line 57—57 of Fig. 56;

Fig. 58 is a similar view but with some of the parts in a different position;

Fig. 59 is a vertical section of a portion of the syruping apparatus on the broken line 59—59 of Fig. 56;

Fig. 60 is a vertical section of the upper end of the syruper on the line 60—60 of Fig. 56;

Fig. 61 is a horizontal section on the line 61—61 of Fig. 58;

Fig. 62 is a horizontal section on the plane of the line 62—62 of Fig. 59;

Fig. 63 is a vertical section, partly in elevation of a detail;

Figs. 64 and 65 are similar vertical sections, partly in elevation, of a detail of the

apparatus, with moving parts in different positions.

In each of the embodiments of my invention chosen for exemplification thereof, the frame of the machine comprises a table on which a rotary bottle carrier is mounted and a standard, carrying the syruper, filling and crowning mechanism, and crown feeding mechanism, the standard being vertically adjustable relatively to the table in order to adapt the machine to bottles of substantially different sizes, for example, quarts, pints, etc., the machines differing only insofar as required to feed the bottles to the carrier by hand in the one case and automatically in the other. I shall therefore first describe the machine in which the bottles are fed to the rotary carrier by hand and thereafter refer to the differences in construction of the automatically fed machine.

Referring first to Figs. 1, 2, and 3 for the general construction of the hand-fed machine, the base or main frame of the machine is shown at *a* and the rotary bottle carrier mounted thereon at *b*. The vertically adjustable standard *c* carries the syruper *d*, the filling and crowning head *e*, the hopper *f* for receiving the crowns to be applied to bottles and feeding them thereto and the mechanism operating and associated with these several devices.

Referring now more particularly to Figs. 2, 3, 4, 48, 49, 50, 51 and 52, it will be seen that the main frame 100 is a hollow casting comprising a flat table top 101, over which the bottles to be filled slide as they are moved by the rotary bottle carrier, and a rear open topped portion 102 over which the vertically adjustable standard *c* is mounted. The table top is formed with a boss 103 in which shaft 104 of the bottle carrier is journaled and the main frame is formed with a boss 105 coaxial therewith in which a second shaft 106 is journaled.

The rear open topped portion of the casting is formed with bosses 107, 108 and 109 through which the lower end of the main driving shaft 110 extends.

The vertically adjustable standard which carries the bottle filling mechanism, etc., as stated above, is in the nature of an elongated shell 111, the skirt 112 of which partially surrounds the open topped rear portion 102 of the main frame, see Fig. 48. It is open at its front at 113, (see Fig. 18) and at 114, and formed on its lower front edges with outward flanges 116 (see Fig. 3) which are guided in channels 117, (see also Fig. 55) on the main frame. The upper end of the adjustable standard is closed by a cap plate 118 bolted thereto and formed with a boss 119 in which the upper end of the main shaft 110 is journaled. The main shaft is also journaled at a point approximately midway its length in a sleeve 120 extending through

and bolted to a horizontal web 121 of said standard. For this purpose the main shaft carries a flanged collar 122 which is secured to the shaft and extends into the sleeve 120, a ball bearing 123 being provided between the flange of the collar and the sleeve.

In order to adjust the standard relatively to the main frame, the sleeve 120 is formed with an external thread 124 which meshes with a sleeve nut 125 journaled in boss 107 of the main frame, above mentioned. The sleeve nut at its upper end is formed with a worm thread 126 which is engaged by a worm 127 on a horizontal shaft 128 journaled in the main frame or casting at 129, and provided with a crank handle 130, (see also Fig. 50). By turning the handle, sleeve 120 and the shell casting are adjusted vertically in an obvious manner.

The lower end of the main shaft is formed with a spline groove 131 and extends through a sleeve 132 splined to said shaft and journaled in the boss 109 in the main frame, above mentioned. A gear 133 is keyed to the last-mentioned sleeve and engages a second gear 134 on a stub-shaft 135, journaled in the boss 136 of the main frame. Said stub-shaft also carries a mutilated gear 137 which meshes with a Geneva movement gear 138 on the lower end of shaft 106, above mentioned, (see also Fig. 49). A jaw clutch 139, which may be of ordinary construction, detachably connects shaft 106 with the bottle carrier shaft 104 and may be opened and closed by means of a fork 140 on a shaft having an exterior handle 141. It will be understood that the bottle carrier is rotated step by step from the main shaft through gears 133, 134 and the Geneva movement above described.

In the machine in which the bottles are fed to the carrier by hand, the bottle carrier consists of two castings, the main casting comprising upper and lower disks 142, 143 having registering bottle openings therein so that the bottles extend through said openings and slide upon the table 101, (see also Figs. 50, 51) and a hub *b'* recessed at its upper end and fixed on shaft 104. The supplemental carrier casting comprises a third disk 144 having open peripheral recesses 145 in registry with the openings 142, 143 and which assist in locating bottles therein, and a depending sleeve 146 secured within the central recess 147 in the main bottle carrier casting. The disk 144 covers said recess in which is located the lubricator oil cup 148 for the bottle carrier shaft.

As it is important that during the filling and crowning operations the lip of each bottle filled shall occupy the same vertical position in order to cooperate properly with the filling mechanism and as the bottles commercially available for packaging beverages and the like, even though of the same lot and ap-

proximate capacity, differ substantially in height, there is provided an automatically adjustable support in the table for holding the bottle being filled. For this purpose the table top is formed with a countersunk circular opening 150 in which is seated the upper end of a cylinder 151, the flange 152 of the cylinder resting in the rabbet or countersink, see Figs. 48, 51, 52. A follower 153 which forms the seat for the bottles when they are being filled, is guided in the upper end of said cylinder and provided with a cushion 155 of a slightly yielding material. A cupped washer 154 surrounds the bottle seat, between which and the flanged guide 156 it is clamped. The lower end of the cylinder is somewhat reduced in diameter and provided with an upwardly projecting sleeve 158, a spring 159 being interposed between the bottom of the cylinder 20 and the guide 156 above mentioned to exert an upward pressure on the bottle seat. A rod 160 is secured to the bottle seat and extends loosely through the sleeve 158 and is guided in a boss 161 of the main frame. At its lower end the rod is formed with a rack 162 meshing with a gear 163 suitably journaled in the main frame. The band pulley 164 is formed with or secured to the gear 163 and receives a brake band 165. The ends of the brake band 30 are secured at 166, 167 to a lever 168 which is pivoted at 169 on the frame. The lever comprises an arm 170 carrying a roller 171, both being shown in dotted lines in Fig. 48, and the roller travels a cam flange 172 on a collar 173 35 fixed on sleeve 174 keyed to the main shaft. The sleeve is journaled in the boss 108 of the main frame, above-mentioned, and is secured against vertical movement by a nut 175 on the upper end thereof and the above-mentioned 40 collar 173 resting on the flange 176 of said sleeve. A coiled tension spring 177 shown in dotted lines in Fig. 48, connected to said arm and to the frame exerts a downward pull on the arm. When the roller is on the lower 45 portion of the cam flange 172, the brake band grips the pulley 164 and prevents rotation of the latter and of the gear 163 attached thereto. When the roller engages the upper portion of the cam, the brake band is slackened, 50 permitting rotation of the gear. The machine is so designed that during the rotary step by step movement of the bottle carrier, the roller 171 is on the upper portion of the cam track and the bottle support under pressure of spring 159 occupies the uppermost position shown in Fig. 48 in which its upper surface is flush with the surface of table 101, further upward movement being prevented by the engagement of the shoulder 178 of the 55 rod 160 with the bottom of the cylinder. As will hereinafter appear the filling head prior to the filling operation descends to a definite position such that it will properly engage the shortest of the bottles of the general size being operated upon. When the filling head 60

gages a bottle which has previously been placed in position on the support by the rotation of the bottle carrier, the bottle support retreats more or less according to the height of the bottle (see Fig. 52). Immediately thereafter the roller 171 on the lever arm drops to the lower portion of the cam under the tension of spring 177 thus locking the gear 163 engaging the rod 160 and so maintaining the bottle support in adjusted position in which it continues until the filling and crowning operations have been completed. Thereafter the rotation of the main shaft with the above-mentioned cam releases the bottle support which is restored by spring 159 to its uppermost position. I shall now describe the bottle-filling and crowning head and its operation and thereafter describe the means by which it is operated. As best seen in Figs. 8 and 10 to 14, 85 inclusive, the head comprises a main casting 200, reciprocated by means hereinafter described, and having a series of communicating co-axial cylindrical chambers therein. A tube 201 for conveying the carbonated water to the bottles extends through the chambers. The upper chamber 204, of smallest diameter, communicates with a passage 205 through which the carbonated water is supplied as will later appear. The upper end of the filling tube 201 is reduced in diameter to fit this chamber 204 and is guided therein. The intermediate chamber 202 is closed at its lower end by a screw plug 203 which is perforated at 206 to form a guide for the filling tube 100 201, above mentioned. Filling tube 201 is formed with an intermediate flange or collar 207 which normally rests upon the plug 203, and a coil spring 208 is interposed between said flange and the upper end of the chamber 105 to exert a downward pressure upon the filling tube and normally maintain it on its seat as shown in Fig. 10. The lower end of the filling tube, which engages the lip of the bottle, is provided with a cushion 209. Within the filling tube is located an air escape tube 210, the upper end of which is screwed in the main filling head casting at 211 and communicates through a channel 212 in said casting with a tube 213, the connection of which will be described, to permit the air to escape from the bottle as it is being filled. The air tube 210 is formed on its exterior with spiral ribs or fins 210' whereby the incoming liquid is given a whirling motion in its descent to the bottle so that by centrifugal action the liquid is thrown against the walls of the bottle and the air escapes through the center. Beneath the plug 203 is a cylindrical chamber 214 containing a similarly shaped block 110 or die holder 215, cylindrically bored at 216 for the reception of a sectional die 217 through which extends the filling tube and which has the function of securing the crown 115 to the bottle lip after the crown has been applied. 120

plied to the latter. The construction of the die can best be gathered from Figs. 10 and 16. It is composed of six longitudinal sections 218 having upper and lower exterior flanges 219, 220, between which flanges is coiled a spring 221 which holds the sections together but permits a slight expansion of the die to allow for irregularities in bottle heads. The spring at its lower end rests upon a ledge or shoulder 222 of the block. The diameter of the bore 216 and the internal diameter of the flange 222 is such as to permit the slight expansion of the die provided by the spring above mentioned. It is to be understood that after a bottle has been filled and a crown placed thereon, the head descends over the bottle head which enters the die and the latter presses the corrugated rim of the crown inwardly to lock it beneath the lip of the bottle.

Immediately below the block 215 is a second block 224 or dial support of somewhat larger diameter; the blocks being held in position by bolts 224' and 225'; see also Figs. 30, 31 and 32. Block 224 is formed with an opening 225 coaxial with the die and filling tube and a diameter such that the heads of the bottles in the operation of clamping or dieing the crowns may pass therethrough. Block 224 is also formed on its upper face with a shallow cylindrical chamber 226 in which fits an oscillating disk or dial 227. The chamber 226 is eccentric to the opening 225 and the disk 227 is formed with a filling opening 228 of less diameter than the head of a bottle and a crowning opening 229 of a diameter to permit a bottle head to pass therethrough, said openings being so located that by oscillation of the dial they may be alternately brought into coaxial relation with the opening 225. Opening 228 is brought into registry therewith when the bottle is to be filled. In the meantime the opening 229 receives a crown to be applied to the bottle and on the next movement of the disk the latter opening is brought into registry with opening 225 so that the crown may be applied to the bottle. Opening 228 is provided with a hard rubber liner 230. Opening 229 is formed with a shoulder or seat 231 having a rounded edge and is of proper diameter, slightly smaller than the extreme diameter of the skirt of a crown to properly support the latter in position. Above the level of shoulder 231 the disk is cut away at 233, Figs. 11, 30 and 31, to provide a channel through which the crown may be inserted, by mechanism provided for the purpose, and located on the seat or shoulder of the opening. The above-mentioned block 215 is formed with a bore or chamber 235 in which is mounted a dog 236 which engages the top edge of a crown after it has been inserted and holds it on the seat (see Figs. 10, 32 and 15). The dog is chamfered

at 237 and pressed down by a spring 238 in the hollow thereof, so that it yields to a crown when the latter is being inserted. As best seen in Fig. 15 the upper body 239 of the dog is cylindrical but the lower part is 70 partially flattened on opposite sides as at 240, the flattened part projecting through a similarly shaped opening from the chamber 235, the dog being thus prevented from turning. The upper face of the disk 227 is formed 75 with an arcuate groove 241, Fig. 30, to permit the disk to move freely about its axis notwithstanding the presence of the dog.

In order to avoid leakage between the filling head and the bottle head during the filling operation I provide a compressible collar 242 of soft rubber or the like formed with upper and lower beads 243, 244, the upper bead being located in a countersink or rabbet 245 formed in the lower face of block 224 85 about the opening 225. The lower bead is received in a similar countersink or rabbet 247 about an opening 248 in the bottom of the sealing cup 249. It is preferable to provide a screw plug 250 in the bottom of the cup 249 and in which this opening is formed, the opening being in axial alignment with the opening 225 in the block 224 as above mentioned. The cylindrical wall of cup 249 embraces the cylindrical edge of block 224 and 90 has an axial sliding engagement therewith, means being provided as hereinafter described for effecting axial relative movement between block 224 and said cup for compressing the rubber collar when the seal between the head and the head of the bottle is to be effected and for permitting the collar to expand when the bottle head is to be released. This means will presently be described. 100

In order to effect a seal between the upper edge 251 of the cup and the main filling head casting during the filling operation, the latter is provided with a soft rubber gasket 253 arranged in a recess therein and surrounding a beaded annulus 254 which directly surrounds the block 215. The beaded annulus is suitably secured to block 215 and holds the rubber gasket in position. The gasket extends slightly below the bottom of the main casting of the filling head, except for the lip 255 of the latter, and when the cup 249 is lifted relatively to the filling head, or more correctly stated, when the latter is lowered, the edge of the cup sufficiently compresses the gasket to secure a tight joint. 110

It will now be convenient to follow the operations of filling and crowning a bottle with reference to Figs. 10 to 14 inclusive, which show successive phases of the operations of the machine. Fig. 10 shows a bottle α in position ready for the filling head to descend upon it. The cup 249 occupies its lowered position with reference to the filling head in which position the rubber seal 242 125 130

is uncompressed, the filling tube 201 is in its lowered position in the filling head and the rotary disk 227 is in that position in which the filling opening 228 therein is in axial alignment with the filling tube 201 and the opening 225 in block 224. The filling head next descends upon the bottle and the latter enters the filling head until its lip is in contact with the liner 230 about the opening 228 of the rotary disk. The filling tube retains its position but the cup 249 after descending with the filling head proper until the hard rubber gasket 230 is in engagement with the lip of the bottle, moves upward until its edge is in close contact with the gasket 253 and the rubber collar 242 is so compressed as to form a tight seal about the head of the bottle, all as seen in Fig. 11. The filling liquid is then discharged into the bottle to the required level after which the filling head lifts or rises slightly to free the rotary disk 227 from contact with the bottle lip, see Fig. 12. In the meantime the above-described seals are maintained. Before the filling head moves downward onto the bottle it has received a bottle crown γ as shown in Fig. 10. After the filling head has risen to the position shown in Fig. 12 the disk carrying the crown revolves partially to bring the crown directly over the bottle and beneath the filling tube as seen in Fig. 13. The filling head next moves downward again until the rubber collar 242 engages the neck of the bottle, while still in compressed condition and the lip of the bottle engages the crown and lifts the same against the bottom edge of the filling tube and lifts the latter against the pressure of its spring 208 whereby the crown enters the die 217 through the rounded mouth thereof and thereby the corrugated skirt of the crown is pressed inward under the lip of the bottle. This completes the filling and crowning operation and thereafter the cup 249 descends, the rubber collar 242 expands, releasing the bottle neck, the filling head is raised and restored to its original position as shown in Fig. 10 and the pressure of the spring on the filling tube restores the latter to normal position, pushing the crowned bottle downwardly to release the crown from the die and permit the filling head to completely clear the bottle.

The main body of the filling head, described above, is cast integral with the slide 260 hereinafter called the auxiliary slide, a neck 261 and web 262 connecting the head with the slide, see Figs. 8 and 9. The slide is formed with sleeves 263, 264 which slide on guide rods 265, 266, carried by the main slide 267 which is formed with pockets 265' into which said rods extend at their upper and lower ends respectively. The auxiliary slide is thus permitted a limited vertical movement with respect to the main slide 267. The main slide

casting is formed with sleeves 271, 272, see Figs. 8, 30, 35 through which extend pillars 273, 274 secured at their upper ends, at 275 and 276 in the casting of the adjustable standard, see Fig. 4, and at their lower ends in the horizontal web 121 of said casting. The pillars guide the main slide in its vertical movement. The main slide is provided with a roller 268 and the auxiliary slide with a roller 269, which rollers operate in grooves in a cam cylinder 277 to be presently described, pinned to the main shaft at 278, and by which vertical movement is imparted to the respective slides, see also Fig. 18. Roller 268 on the main slide operates in the upper groove 279 of the cam cylinder and roller 269 of the auxiliary slide operates in the lower groove 280 thereof. The layout of these cam grooves will be later explained in connection with Fig. 17 of the drawings.

A worm wheel 282 revolves freely on the main shaft 110 and is engaged by a worm 283 on a horizontal shaft 284, suitably journaled in the adjustable standard casting and carrying a sprocket 285 by which it may be driven from the motor 28^a through chain 28^b, see Fig. 3. A hand wheel 286 is also provided for turning the shaft by hand when desired.

A clutch mechanism to be now described, is provided for connecting and disconnecting the main shaft 110 with the worm wheel 282. The latter is provided with the female member 288 of a cone clutch, which is bolted to the worm gear 289. The male member 290 of the cone clutch is bolted to a sleeve 291 which is splined upon a flanged sleeve 292 bolted to the cam cylinder and surrounding the main shaft, see also Figs. 25, 26. The sleeve 291 is formed with an annular series of pockets 293 in which are contained coiled springs 294 bearing at the lower end against the flange 295 of sleeve 292 and at the upper end against the bottoms of the respective pockets. Thus the springs tend to hold the male member of the clutch in engagement with the female member. The clutch, however, is opened or released to stop the revolution of the main shaft and its associated parts when the filling head reaches the filling position. For this purpose a swinging, semi-circumferential yoke 296 is pivoted at its ends to the standard casting and engages the male member of the clutch. The yoke comprises an outer flange 298, terminating in eyes 299 receiving pivot bolts 300 and an inner flange 301, terminating in eyes 302, which receive the trunnions 303 of rollers 304. Rollers 304 ride upon an annular track 297 carried by flange 305 of sleeve 291, above mentioned. Thus when the yoke is drawn downward, as presently described, the rollers bearing upon the track depress the male member of the clutch and disengage it from the female member.

As best seen in Figs. 17, 23, and 24, provision is made for definitely arresting the ro-

tation of the main shaft and cam cylinder immediately after the clutch is opened. For this purpose the upper end of the cam cylinder is cut away at 309 and recessed at 310 to receive an insert 311 of hardened metal which presents an abrupt but slightly inclined shoulder at 312. The yoke 296, mentioned above, is provided on its bottom edge, adjacent the middle, with a hardened insert 313, shown in full lines in Fig. 23, and in dotted lines in Fig. 24, which is inclined downwardly and so arranged that when the yoke is in its lower position the edge of the block 313 will encounter the shoulder block 311 on the cam cylinder to positively arrest the latter and the main shaft.

At about the middle of the yoke is an insert 306 of hardened metal having a lip 307 extending outwardly and upwardly for engagement with a hook member 314 by which the yoke is swung downward at the proper time to open the clutch. Hook 314 is so mounted on the main slide as to be carried up and down thereby and also to have a swinging movement toward and from the yoke, so that when in the forward position the hook cannot engage the yoke but in the rearward position it engages the lip of the latter and swings the yoke downward with the descent of the main slide. The construction and mounting of the hook 314 is best seen in Figs. 4, 18, 19, 20, 21 and 23. The hook 314 is adjustably mounted on a short rod 315 extending upwardly from a perforated boss 316, see Fig. 23. The boss is pinned to a bolt 317 journaled in bosses 318, 319 on the ends of arms 320, 321 of a bell crank carrier 322. Such carrier is in turn pivoted on a bolt 333 extending through ears 335, 336 formed on the main slide casting, above mentioned. The bolt 317 extends through and beyond the arm 321 of the bell crank casting and carries on its end a casting 337. Said casting comprises, in addition to the barrel which receives the bolt 317 and is secured thereto, a handle 338 and two downwardly projecting arms 339, 340. The extremity of the arm 340 is connected by coiled tension spring 341 with an eye 342 which is stationary with respect to the main slide casting, being formed upon casting 343 carried by the main slide and which will be described later. The arm 339 carries an adjustable contact 344 which is held in contact with the end of a rod 418 by the spring just mentioned. Said rod is normally in the retracted position shown in Fig. 18 but when the filling of the bottle is completed it is thrust rearwardly in a manner hereinafter described, against the contact 344 thereby swinging the structure on pin 317 including the hook 314 to release it from the yoke and permit the latter to rise. The forward swinging of the hook 314 is limited by the engagement of

a stop 345 on the casting 337 with stop 346 on the casting 322.

Casting 322 above mentioned is formed with a forwardly projecting arm 347 which is connected by a link 348 with the bell crank lever 349 pivoted on the main slide at 350, see particularly Figs. 4, 8, 20 and 21. The bell crank carries a roller 351 which is in engagement with the cam 352 carried by the supplemental slide, see particularly Figs. 4 and 20. Cam 352 is an internally threaded annulus screwed upon the upper end of a guide sleeve 353 of the auxiliary slide casting, said cam having a lower portion 354 of larger diameter and an upper tapered portion 355. When the main slide carrying the casting 322, the bell crank lever 349 and the connecting link 348 moves downwardly with reference to the auxiliary slide carrying the cam 352, the bell crank lever is swung outwardly by the cam, lifting the link 348 and swinging the casting 322 rearwardly or toward the clutch shifting yoke. On the other hand when the main slide rises with respect to the auxiliary slide, the roller of the bell crank lever rides up onto the reduced tapered portion of the cam which permits casting 322 to which the yoke engaging hook is pivoted to fall back away from the yoke.

Normally, the position of the parts just described is that shown in Figs. 18 and 20, the roller 351, being upon the reduced portion of the cam and the casting 322 consequently being in the forward position away from the clutch. At the same time the rod 418 is in the forward or retracted position. When the filling head descends to engage a bottle to be filled, the main and auxiliary slides move together until the filling head, which is carried directly by the auxiliary slide, as heretofore stated, engages the lip of the bottle. The further descent of the auxiliary slide is then arrested and the main slide continues its descent a little further, as will be more fully described below. This relative movement of the main slide causes the roller 351 to move downward upon the portion of the cam 352 of larger diameter and thus throws the casting 322 carrying the hook structure toward the yoke. At the same time, the contact 344 being held against the retracted rod 418 by the action of a tension spring 341, the hook 314 tilts rearward into the path of the engaging lip on the yoke, as seen in Fig. 19. The hook therefore engages the lip of the yoke as the main slide completes its descent and, drawing the latter downward, opens the clutch as shown in Fig. 19.

The parts remain in the position shown in the last named figure until the bottle is filled. The air escaping from the bottle drives the rod 418 rearwardly as the liquid reaches the desired level in the bottle, thus swinging the hook-carrying assembly in its bearings in the

casting 322 to release the yoke and permit the clutch to close whereupon the revolution of the main shaft and the parts driven thereby is resumed. The means whereby rod 418 is operated will now be described particularly with reference to Figs. 1 to 8 inclusive, 18 to 22 inclusive and Figs. 27 and 28.

Referring first to Fig. 8, a casting 343 mounted on the main slide comprises an interiorly threaded nipple 361 projecting downwardly through a perforated projection 362 of the main slide casting and said nipple is interiorly threaded to receive a guide sleeve 363. The latter extends into the guide sleeve 353 of the filling head heretofore mentioned. The air outlet tube 213 communicating with the air escape tube 210 of the filling head, extends through sleeve 363 and casting 343 and is coupled, at its upper end, to a flexible tube 364 which in turn is coupled at 365 to a screen housing 366, see Fig. 27. Housing 366 contains a screen 367 and is connected by union 368 and elbow 369 with passage 370 of housing 371 of the air pressure control device, Figs. 22 and 28.

Said passage 370 communicates with the inlet chamber 372 of said housing, which is separated from the outlet chamber 373 of the housing by a septum 374. Said septum contains a valve seat 375 for a valve 376, the construction and operation of which will be described later. The housing also comprises an upwardly extending cylinder 373' with which chamber 372 communicates. A hollow boss 371', the passage 372' of which communicates with the outlet chamber 373, extends into the center of the housing and is perforated and threaded at 377 for the reception of the lower end of an exhaust regulator tube 378. Said tube is formed with a head 379, having a valve seat 380, and also is formed on its exterior with longitudinally extending grooves 381 which gradually contract from their lower to their upper ends, see Figs. 28 and 29. A controller 382 slides upon the tube 378 and cooperates with the grooves and the valve seat thereof to control the passage of air from the inlet chamber to the outlet chamber previously described. It comprises a casting 383 formed with a sleeve 383 surrounding the grooved tube and sliding thereon, and a chambered head 384 containing a valve packing or washer 385 with which the valve seat of said tube cooperates. An annular, flexible diaphragm 386 is interposed between the controller and the housing, its inner beaded edge 387 being clamped between the head of the casting and a washer 388 surrounding the sleeve portion of the controller and held in place by a nut 389 thereon. The outer beaded edge 390 of the diaphragm is clamped between a seat or shoulder 391 formed on the interior of the housing and a grooved washer 392 engaged by a sleeve 393 threaded into said housing. The diaphragm closes communication

between the lower and the upper portions of the housing except through the controller. A spring 394 is interposed between the nut on the controller and a shoulder 395 on the housing, said spring being under compression and tending to close the controller against the head of the tube. A more powerful spring 396 is interposed between the upper edge of the controller head and an adjustable abutment 397 in the upper end of the housing and exerts its pressure to resist the upward movement of the controller. The adjustable abutment 397 is in the nature of a washer, the upper face of which has a conical cavity 398 which receives a seat 399 on a plug 400 screwed into the upper end of the cylinder and adjustable therein. The plug is formed with a squared extension 401 which receives the cap 402 held in place thereon by a nut 403. The cap is formed with a serrated edge 404 for revolving it to screw the plug in or out to adjust the pressure of the spring, and also for engagement by a spring 402^a to hold the cap in adjusted position.

The operation of the air exhaust control just described is as follows: With the valve 376 in the open position shown in Fig. 28, there is, of course, an open passage from the inlet to the outlet chamber so that the control mechanism is idle and ineffective. During the filling operation, however, as will presently appear, the valve 376 is closed and the only escape for the air from the bottle through this apparatus from the inlet to the outlet chamber thereof is through the grooves 381 in the controller tube 378, the upper space of the cylinder and the bore of the tube. Normally the pressure of the spring 396 overbalances the pressure of the spring 394 so as to hold the controller 382 in lowered position with the upper edge of its sleeve at a level where the grooves 381 are of larger cross section, and the valve washer or seat remote from the head of the tube. Thus air reaching the inlet chamber from the bottle in small volumes as the bottle begins to fill may escape through the grooves 381, washer 385, the upper end of the cylinder, the bore 406 of said tube, passage 372', and outlet chamber 373. When the rush of air from the bottle increases however, the passages 381 of the stem 378 being insufficient to provide for its free escape, the pressure in the inlet chamber and beneath the diaphragm rises. With the rising pressure, the movable control member is forced upward against the pressure of spring 396, the upper edge thereof throttling the escape of air as it moves to levels at which the cross sectional area of the grooves 381 is less. The passages for the escape of air being thus progressively reduced, the pressure beneath the diaphragm rises rapidly and ultimately the controller reaches a position in which the valve washer closes against seat 380, shutting

off the escape of air causing the pressure to rise rapidly.

The inlet chamber 372 is connected to the cylinder of the motor by which the rod 418 mentioned above is actuated to trip the hook 314 to release the clutch opening device or yoke.

Referring now more particularly to Figs. 20, 21, 22 and 28, the motor referred to above comprises a casting 343 mounted on the main slide casting by a flange 412 bolted to the latter. The casting is bored to provide a cylinder 410 which is in communication with the inlet chamber 372 of the control device, previously described, through a passage 413 extending into the head 414 of the cylinder and communicating with the interior thereof. As best seen in Figs. 22 and 28 the passage 413 comprises a horizontal member communicating at one end with the inlet chamber of the control device, a short vertical member 41^a and a short horizontal member 41^b. The latter enters the chamber 410 below the segmental block 41^c as best seen in Fig. 20.

The cylinder 410 contains a piston 417, to which the hook-tripping rod 418 heretofore mentioned is connected. The rod extends through a plug 419 in the rear end of the cylinder and engages the contact of the arm 339 heretofore mentioned to control the position of the hook by means of which the clutch is opened, as previously described. A spring 420 is under compression between the piston and plug for normally maintaining the former in its forward or retracted position. When the pressure in the control device rises approximately to the maximum due to the air driven out from the bottle in filling the latter, as previously explained, the cylinder 410 being in open communication with the control device, the pressure of air from the latter drives the piston rearward and through the mechanism previously explained withdraws the hook from engagement with the yoke.

Inasmuch as the pressure of and on the carbonated water with which the bottles are being filled and the gas thereof is subject to some fluctuation, and the pressure of the air in the control device and cylinder 410 varies accordingly, were provision not made to the contrary, the trip mechanism just described would operate earlier or later in the filling operation, according to such variations in pressure and the level of the liquid in the bottles would vary somewhat accordingly. To obviate this difficulty, I vary the pressure on the spring 420 according to the pressure of the liquid being filled. For this purpose, the plug 419 has a sliding fit in the cylinder 410. Beyond the end of the cylinder, the plug is formed with a reduced neck 425 which is engaged on its respectively opposite sides by pins 426 carried by the respective arms of a bifurcated lever 427. This lever is pivoted

at 428 on the casting 343 and at the end thereof opposite that which engages the sliding plug is pivoted at 429 to the rod 430 of a piston 431. Piston 431 slides in a cylinder 432 also formed in casting 343, the rear end of the cylinder being closed by a screw plug 433 between which plug and the piston is compressed a coiled spring 434. The front end of the cylinder is closed by a cap 435. A pipe 436 communicates with the space within the cylinder between the cap and the piston and extends around the side and rear of the machine and connects, in a manner to be presently described, with the head of the supply reservoir for the carbonated water in such manner as to be open to the pressure prevailing in the reservoir, see also Figs. 1, 2 and 3. Referring again to Fig. 20, it will be seen that the position of the piston 431 in cylinder 432 depends on the pressure communicated to said cylinder through pipe 436 from the liquid reservoir, and the piston through its rod and the lever 427 correspondingly controls the position of the plug 419 against which spring 420 in cylinder 410 bears. Thus, the counterpressure of said spring on the piston 417 is varied correspondingly to fluctuations in the air pressure by which the piston is operated and the clutch is always tripped at the same predetermined liquid level in the bottle irrespective of the minor variations in the pressure of the liquid being handled.

I have heretofore referred to the fact that the valve 376 in the control device is normally open, but is closed during the filling operation. The valve is operated through its stem 440 which extends through a stuffing box 441 in the bottom of housing 371 and is provided with a button 442 on its lower end, between which and the gland of the stuffing box is compressed a coiled spring 443, see Fig. 28. Referring now more particularly to Figs. 18 and 20, it will be seen that the link 348, heretofore mentioned, is formed with an extension 444 in which is adjustably mounted a tappet 445, immediately below the button 442. When the auxiliary slide carrying the filling head is arrested in its downward movement while the main slide continues to descend, as previously explained, and the roller 351 of the bell crank 349 moves downward over the enlarged portion of the cam 352, the link 348 being thrown upward, the tappet 445 engages the button 442 and lifts valve 376 to its seat against the pressure of spring 443. Valve 376 is thus maintained in closed position until the filling operation is completed and until after the hook is disengaged from the clutch opening yoke by the pressure of the air from the bottle acting on piston 417. When the main slide moves upward with respect to the auxiliary slide and the roller of bell crank 349 drops back on to the portion of cam 352 of less diameter, arm or extension 444 falls to release

the valve and permit it to open under the pressure of the spring.

I have hitherto explained in connection with Figs. 10 to 14, inclusive, the movement of cap 249 to compress the sealing gasket 242 after the filling head has descended into engagement with the bottle lip, in order to seal the filling head to the bottle head. The movement of the cup is controlled by the relative movement between the main and auxiliary slides. Referring now to Figs. 1, 5, 6 and 8, in which the connections for accomplishing this movement are best shown, it will be observed that a bell crank lever 450 is fulcrumed at 451 on a link 452 which latter is pivoted at 453 to the filling head casting and limited in its movements by nuts 45^b and a spring 45^c on a bolt 45^d screwed into the filling head against which the spring bears. Lever 450 is bifurcated, the forks 454 thereof extending respectively to the front and rear of the filling head. To the front arm 454 is pivoted at 456 a pair of blades 457, 458, each of which is notched, the former on its left-hand edge at 459 and the latter on its right-hand edge at 460, see dotted lines Fig. 6. The respective notches receive a headed pin 461 on the flange or cylindrical portion of cup 249, the blades partially overlapping. Each of the blades is also formed with a slot, that in the front blade 457 being shown in Fig. 6 at 462. When the blades are assembled in operative position, the slots therein coincide and embrace a removable screw bolt 463 which extends therethrough and is screwed into the head casting, thus locking the blades in position but the slots are of sufficient length to permit the requisite relative vertical movement between said blades and the filling head. A second pair of blades 464, 465 is pivoted at 466 to the rear fork of the lever, said blades being partially offset respectively to the left and right to pass on opposite sides of the neck 261 and web 262 of the auxiliary slide casting, see Figs. 6, 7 and 8.

As seen in Fig. 6, blades 464, 465 are formed in the outer edges and near the lower ends thereof with notches 468, 469, respectively, see dotted lines Fig. 7, which receive the necks of studs 470—471 on bosses 472, 473 extending rearwardly from the cup, see also Fig. 30. In order to lock blades 464, 465 in engagement with studs 470, 471, the lower end of blade 464 has pivoted thereto a link 474 and to the end of blade 465 is pivoted a link 475, see Figs. 6, 7, 8 and 33. The links overlap and are pivoted together by a pivot pin 477. Link 475 is extended beyond the pivot and formed with a thumb piece 480. It is also provided with a pin 481 having a rounded end which yieldably engages a depression 482 in link 474 to normally hold the link in the position shown, thereby holding the blades 464, 465 in engagement with the respective studs 470, 471. By pressing down on the thumb

piece 480 the links are caused to buckle downward, the pin 481 sliding out of its seat or depression and thus the blades 464, 465 are caused to approach each other to an extent which frees them from the respective studs 470, 471. Thus for adjustment, repair, or the like, the cup may be readily disengaged from the blades by which it is connected to lever 450.

Arm 483 of lever 450 is provided with a roller 484 for engagement with a swinging cam 485, see Fig. 6. This cam is pivoted by bolt 486 between lugs on the main slide casting of which the front lug is shown at 487 in Figs. 7 and 9. When the filling head is in its upper position and the main slide is in its upper position with respect to the auxiliary slide, the roller of the swinging cam rests against the reduced portion of the annular cam 355 above described, and consequently lever 450 is in the position shown in Fig. 7, in which the cup is lowered relatively to the filling head and the rubber seal expanded. When, however, the filling head descends and is arrested in filling position and the main slide descends further relatively to the auxiliary slide, the roller on cam 485 descends to the portion of cam 352 of greater diameter, swinging the cam outwardly and swinging bell crank lever 450 to cause it to lift cup 459 into the position in which the sealing sleeve or gasket is compressed, as seen in Figs. 11 to 14, inclusive.

Referring now more particularly to Figs. 8, 17, 18 and 19, the motion of the main and auxiliary slides will readily appear from the construction of the cam cylinder. The cylinder rotates in the direction of the arrows. The track or groove of the roller 268 on the main slide is indicated at 279 and that of the roller 269 on the auxiliary slide at 280. Assuming the slides to be in their uppermost position with the rollers thereof in their respective grooves at the left of the layout in Fig. 17, and the filling head parts in the position shown in Figs. 10 and 18, the rotation of the cam causes the two slides to descend together without relative movement until the rollers reach the position marked AA'. Beyond this line, the lower walls of the respective grooves continue parallel as at BB'. The upper wall of the auxiliary slide groove 280 however is substantially horizontal as at C' while the corresponding wall of the main slide groove inclines downwardly as at C. When the position AA' is reached by the rollers the filling head has engaged the lip of the bottle on the bottle seat beneath. The bottle is slightly depressed more or less, according to its height, as heretofore stated, the bottle seat yielding to this extent and then being locked against further descent. The horizontal portion C' of the upper wall of the auxiliary slide groove permits the filling head to remain during the portion of movement of

the cam immediately following without substantial vertical movement. The portion C of the upper wall of the main slide groove, however, forces the main slide to a further descent independently of the auxiliary slide and filling head, and during this descent bell crank 349 is rocked, as previously described, to throw the hook 314 into position to engage the clutch-opening yoke and the swinging cam is rocked to lift the cup 249 and compress the rubber seal about the head of the bottle, as previously described. At the end of the descent of the main slide, the hook, which as before stated, is carried thereby, engages the yoke, tilting it downward to open the clutch, the main shaft and cam cylinder thereon, as well as the other moving parts, coming to rest, the shoulders on the yoke and cam cylinder, as previously explained, stopping further movement due to momentum of the parts. The main slide roller during the period of rest is located immediately below the concave portion D of the upper wall of the groove 279. The parts are then in the position shown in Figs. 11 and 19. When the movement of the cam cylinder is resumed, after the filling is completed and after the hook has been tripped as above described, to permit the clutch to close, the rise H on the lower wall of the groove 280 slightly raises the filling head to the position shown in Fig. 12 to release its disk 227 from the pressure of the bottle lip, thus permitting it to revolve for the purpose of bringing the crown thereon over the bottle, as seen in Fig. 13, and to permit the pressure to equalize itself throughout the filling head. As the inclines EE' of the upper walls of the respective grooves reach the rollers, the slides are depressed further, at first for a short distance together and then the auxiliary slide continues its descent alone while the main slide briefly remains stationary. The further descent of the auxiliary slide and the filling head carries the seal down on the neck of the bottle and forces the die in the filling head downwardly over the crown on the bottle to the position shown in Fig. 14, thereby attaching the crown to the bottle, the filling tube in the meantime yielding upwardly against the pressure of its spring and maintaining the crown firmly on the bottle lip. This relative movement between the slides slightly relieves the pressure on seal 242 by lowering cup 249. The further descent of the auxiliary slide carries the seal down onto the neck of the bottle and the die in the filling head downwardly over the crown on the bottle, see Fig. 14. As the cam cylinder rotates further the rollers travel up the incline portions FF' of the track and the main and auxiliary slides are thus raised together. Thereafter the horizontal portions GG' of the grooves travel over the respective rollers which remain stationary holding the slides in their uppermost positions. Prefer-

ably the cam cylinder is provided with inserts 492, 493 and 494 of hardened metal at the points of greatest wear.

The cam cylinder also controls the movement of the oscillatory disc or dial 227, oscillating it from the position shown in Figs. 10, 11, 12 and 31 in which filling takes place, to that shown in Figs. 13, 14 in which the crown is presented over the lip of the bottle and affixed to the latter, see also Fig. 30. For this purpose a bell crank lever 500, carried by the main slide is horizontally operated by engagement with the cam cylinder and is so connected to the dial or disc as to oscillate the latter when rocked, see Figs. 30, 31, 32, 35 and 36. In order to provide a bearing or fulcrum for the lever, the sleeve 272 of the main slide which surrounds column 273 is cut away at 507 to receive the hub 501 of lever 500 and also the hub 512 of another lever to be presently described. A thin sleeve or bushing 506 surrounds column 273 and extends across the cut away portion or gap in sleeve 272. Said bushing is formed at its lower end with a flange 508 which is received in a rabbet in the lower end of the sleeve 272 and the upper end of the bushing is threaded at 509 to receive a nut 510, see Fig. 36. The hub 512 is reduced in diameter at its upper end and the hub 501 of lever 500 is similarly counterbored at its lower end so that the hub 501 overlaps the upper end of hub 512. Washers 515, 516, 517 properly space the hubs from each other and from the adjacent portions of the sleeve 272. Thus, lever 500 is journaled upon bushing 506 and travels with the main slide. The shorter arm of lever 500 carries a roller 503 at its end which roller travels on the track 544 of the cam cylinder. Said track parallels the track of the main slide roller. The roller 503 is thus enabled to follow track 544 notwithstanding the movement of the main slide with which it is associated. The track 544 is cammed radially to rock the lever 500 at the proper time. Roller 503 is maintained in contact with track 544 by spring pressure. As seen in Figs. 32 and 35, hub 501 is formed with a seat 520, hollow on one side, which receives the rounded end of rod 521. A coil spring 522 surrounds said rod and extends into a pocket 524 of the main slide casting, the outer end of which pocket is closed by screw plug 525 between which and a collar 518 on the rod the spring is compressed. Thus the spring maintains roller 503 in contact with track 544.

The longer arm 504 of said lever is bifurcated at its end and between the upper and lower forks 526, 527 thereof extends a vertical pin 528, see also Fig. 6. A horizontal slide rod 529 extending through the filling head and block 215 thereof is formed with a transversely slotted head 530 through the slot 531 of which the rod 528 extends. By

reason of this connection rod 529 is reciprocated by the lever and it is free to partake of the movement of the auxiliary slide independently of the main slide on which lever 500 is mounted. A stuffing box 534 and a cap 532, the latter surrounding the end of the rod 529, prevent leaking. As best seen in Figs. 8 and 32, the passage 535 in block 215 through which the rod extends is of rectangular and relatively large cross section and a slide block 536 of similar cross section is secured to the rod and travels therewith in said passage. Passage 535 is open at the bottom and a pin 537 on the sliding block extends downwardly therefrom and is journaled in a second sliding block or traveler 538 arranged to reciprocate in a radial slot 539 in the dial or disc 227, see also Fig. 30. Block 539 is rabbeted at its edges at 540 and the block 538 formed with flanges which occupy the rabbets.

From the foregoing it will be evident that as the lever 500 is rocked by the cam, the rod 529 and block 536 are reciprocated and, through the medium of pin 537 and traveler 538, oscillate the dial 227 which is thereby caused to travel between the position shown in Figs. 10, 11, 12 and 31, in which filling takes place and the position shown in Figs. 13, 14 and 32 in which crowning of the bottle takes place, as previously described. The cam track 544 is so designed that normally the roller 503 is on the portion of the track of less diameter and consequently the filling opening of the dial is over the bottle receiving opening in the filling head, and the cut away portion 233 of the dial is in registry with the lateral opening 550 through block 224, in which position of the dial the crowns are fed thereto by the crown delivery mechanism to be presently described. After the filling of a bottle is completed and the rotation of the cam cylinder is resumed, as previously described, the portion of track 544 of larger diameter as at 544^a oscillates the lever to move the dial to the crowning position and after the crown has been secured to the bottle lip and the two slides and filling head have partially completed their ascent, the portion 544^a of the track moves away from roller 503 and permits the dial to be returned, under the influence of the spring 522 to normal position.

In case for any reason the spring 522 fails to return the lever 500 to normal position, the return is accomplished by positively acting means. To this end a pin 50^a attached to the hub 501 of the lever carries a roller 50^b intermediate collars 50^c, 50^d on said pin, see Fig. 32. A cam 50^e is mounted on crown delivery casting bracket 554, to be presently described, said cam being so located and designed, as seen in Fig. 38, that when the lever rises with the slide on which it is mounted, unless the spring has returned the lever to

normal position, the roller thereon contacts with the cam and thereby forces the return of the lever to normal position.

The crown delivery device for placing the crowns in the seat 229 of the rotary disk or dial will now be described. As heretofore stated and as shown in Figs. 10 to 12, 30 and 31, the disk or dial is cut away between the crown seat 229 and the edge of the disk to approximately the level of the crown seat 75 as shown at 233. Furthermore, the block 224 in which the dial is seated is likewise cut away to the same level at 550 so that when the dial is in the filling position as shown in Figs. 10 and 31 and the sealing cup 80 is down, there is a level passage from the edge of block 224 to the crown seat with parallel walls 551, 552 through which, by means to be now described, a crown may be pushed onto the crown seat. This operation 85 of the crown delivery device is effected by a pusher 553. The outlet of this device, through which the pusher reciprocates is so located as to be in registry with said crown 90 passage of the filling head when the latter is in the upper position, as in Fig. 10, at which time cup 249 is in its lower position relative to the filling head to afford a free 95 passage for the crown and pusher. Means to be presently described are provided for feeding the crowns successively and one at a time into the path of the pusher in proper position to be delivered by the latter onto the crown seat. The crown delivery device 100 comprises a bracket 554 which is bolted at 555 to the side of the standard *c*, see Figs. 2, 5, 7, 30 and 35 and extends forwardly of the machine as at 556, and an upper member 557 and a lower member 558 of said casting extend inwardly from the bracket over the 105 front of the machine and are connected by a vertical member 559 and a curved member 560.

The curved member 560 is channeled on its outer side at 582 to form a crown chute 110 through which crowns are fed from an apparatus to be presently described into position to be engaged by the pusher. The upper end of the crown chute is closed by a cover plate 583 to which a swinging door 584 is pivoted at 585, see Fig. 6. A spring catch 587 is provided for normally keeping the door closed but it may be readily opened in case the crowns should get stuck in the chute. Below the door is a fixed cover section 115 588. The pusher 553 is guided in a housing 562 cast with an arm 563 by which the housing is removably secured to member 558 of the casting, see Figs. 15, 10 and 35. The latter is provided on its front face with a short horizontal dove-tail guide 564 and the inner face of arm 563 is formed with a similarly shaped undercut groove so that arm 563 may be slid over guide 564 to bring the housing 562 containing the pusher into suit- 120 125 130

able relation to the other parts of the machine. Arm 563 is provided with a locking screw 566 the inner end of which bears upon the guide 564 to lock the housing in adjusted position.

As best seen in Figs. 5 and 7, housing 562 comprises a top wall 567 and side walls 568 the latter being formed with inwardly projecting ledges or flanges 569 with an open slot between said ledges. The pusher 553 rests on the ledges 569 and is guided in said housing in its reciprocating movement. A block or strip 570 is adjustably secured to the bottom of the pusher by screws 580 extending through slots 581, see dotted lines Fig. 31. A vertical rod 571 is secured to the strip 570 and extends downwardly therefrom and through a perforation in block 572 which slides freely on said rod, see Figs. 35 and 31. Block 572 is guided in a slot 573 in the end of a bell crank lever 574 comprising the hub 512, heretofore mentioned. The shorter arm 575 of the last mentioned lever carries a roller 576 which bears upon the track 577 of the cam cylinder previously described, see Figs. 17 and 31. By reference to the latter figure it will be seen that trackway 577 is parallel to trackways 544 and 279 so that the roller which partakes of the motion of the main slide may follow the track during the revolution of the cam cylinder and the reciprocation of the main slide. The lever is oscillated by the radial variation in the cam track 577 and this is so formed that the lever is normally in the position shown in Fig. 31 in which the pusher is retracted. But when the filling head is in the upper position shown in Fig. 10, with its crown passage in register with the delivery opening, the revolution of the cam cylinder brings the cam portion 578 of the track 577 opposite the roller on the lever. The lever is then actuated by its spring 579, which is similar in respect to its construction and mounting to spring 522 above described, to project the pusher forwardly and through the crown passage in block 224 and disk 227, to push a crown, (which, in the meantime, has been fed into a position immediately in advance of the pusher by a mechanism to be presently described), onto the crown seat 229 of the dial.

As seen in Fig. 6 a filling block 589 is secured to housing 562, the front of the block being cut away on the top to continue the curve and slope of the chute and the bottom of the block which is on a level with the bottom of member 558, constitutes a continuation of the top of the pusher guide or housing 562. The side walls of the housing 562 terminate just short of the filling head but are cut away internally as at 590—591 to an extent sufficient to permit a crown to pass between the same, see Fig. 30. The bottom of the crown passage adjacent the filling head is formed by a tilting block or tumbler

592 having a trunnion 593 which is journaled in a boss 594 of the housing. The upper surface of the tilting block or tumbler is in two planes 594', 595 at an obtuse angle to each other and the block is oscillated by means to be presently described from the position shown in Fig. 7 in which the surface 594' is level and in which position of the block a crown thereon may be delivered by the pusher to the filling head, to a position in which the front end of the block is tilted downward and the rear surface 595 thereof forms in effect a continuation of the bottom of the crown channel, see Fig. 6. As shown in Figs. 30 and 35, the trunnion extends beyond the boss 594 and at its front end carries an arm 598 with a finger piece 599 and a coil spring 600 surrounds the boss and at its end 601 bears against the arm 598. A stop pin 602 is so arranged on the housing as to arrest the arm when, under the pressure of the spring, the tilting block or tumbler is in the position shown in Figs. 7 and 10, for delivery of a crown to the filling head. The tumbler or tilting block is tilted downward into the position shown in Fig. 11 and in which it receives a crown from the crown chute, by a wear plate 603 on the filling head, hereafter described, which engages the nose of the tumbler, on the descent of the filling head.

It will be observed in Fig. 30 that the sealing cup 249 is thickened at 604 and flattened at 605 so as to extend closely along the lip of the tumbler thus providing a substantially continuous support for a crown from the tumbler, and the rear portion or tail-piece 594^a of the tumbler is of reduced breadth as compared to the main portion of the tumbler so that it may enter between the ledges 569 of the pusher housing or guide as shown in full lines in Fig. 30.

The front edge of the pusher is cut out at 606 to substantially conform to the curvature of the skirt of the crowns to be delivered thereby and is undercut at 607 so that it engages the skirt of the crowns somewhat above the lower edges thereof. The upper face of the pusher is slightly hollowed out at 608 so that as each successive crown descends thereon its advanced edge partially enters the groove or hollow as shown in Fig. 10. Furthermore, the side edges of the channelled face of the pusher are cut down adjacent the front end thereof as at 608, see Figs. 10 and 30.

After a crown is in position on the tumbler to be delivered to the filling head and during the delivery operation the other crowns in the crown chute are held back by a dog 609 which projects into the crown delivery passage for this purpose. As seen in Figs. 6, 7, 10 and 11, the dog 609 is generally cylindrical in shape, and is guided in a vertical bushing 60^c in the main casting of the delivery device. In order to prevent turning it

is grooved at 611 and a pin, not shown, projects through the bushing into the groove. The dog is cut away at 611^a so that only a relatively thin projecting portion or blade 613 thereof enters the crown channel. An operating rod 614 is secured in the upper end of the dog and is guided at its upper end in a bushing 615 in the delivery casting. A collar 616 on the rod limits the downward movement of the dog, preventing the blade portion 613 from engaging the pusher and a spring 617 interposed between said collar and the lower end of the bushing 615 normally holds the dog in its lowermost position. The upper end of the rod 614 is threaded at 618 to receive a casting comprising an internally threaded sleeve 619 and a cross head 620. The casting is locked in adjusted position on the rod by a bolt 621 threaded through the casting and engaging the upper end of the rod, a lock nut 622 being provided for preventing the bolt from turning. The dog is raised to permit the downward movement of the crowns in the chute when the filling head is lowered as in Fig. 6 and the tumbler is tilted, the downward movement of the crowns being arrested by the contact of the lowermost one with the wear plate 603 above mentioned. The raising of the dog is effected by means of a tappet 623. This tappet is pivoted on a pin 624 extending between lugs on the main slide casting, see Figs. 1, 6, 7, 9, 18 and 19. The free end 625 of the tappet is bifurcated, the distance between the forks and the length of the tappet being such that when the tappet is in the inclined position shown in Fig. 7 it will pass by the cross head 620, just described, without touching the latter, as the main slide carrying the tappet is raised and lowered, but when the tappet is thrown up into the position shown in Fig. 6, the forks of the tappet will straddle the sleeve 619 and engage beneath the cross head 620 to raise the dog. The tappet 623 carries a roller 626 which moves upon the annular cam 352 heretofore mentioned, carried by the filling head. So long as the auxiliary slide and filling head are in lowered position with reference to the main slide, the tappet occupies the position shown in Fig. 7. But when the filling head is arrested by contact with the bottle and the main slide completes its descent, the roller 626 moves from the upper to the lower portion of cam 352 causing the tappet 623 to engage cross head 620 and raise the dog, thus permitting the crowns in the chute to move downward until the lowermost crown engages the wear plate 603 as above described. The dog is held in the raised position until the upward movement of the main slide relative to the filling head permits the tappet to drop back to its lowered or inclined position, whereupon the dog drops onto the rear top edge of the lowermost crown. When the upward movement of the

wear plate 603 with the filling head releases the nose of the tumbler, the latter is moved by its spring to the position shown in Fig. 7 in which the machine is ready to deliver the crown on the tumbler to the filling head. As the cam cylinder continues its revolution the elevation on the cam track 577 swings the lever 574 to actuate the pusher which then forces the crown from beneath the dog and delivers it to the crown seat of the dial of the filling head and then retires to normal position. As the crown on the tumbler is pushed from beneath the dog, the latter drops until arrested by the collar 616 engaging the crown delivery casting, the dog then being in position to hold back the other crowns in the chute until said dog is again elevated by the descent of the main slide as above described.

The wear plate 603, to which reference has been made, and which tilts the tumbler on the descent of the filling head and also arrests the descent of the crowns when the dog is raised, is carried by the filling head casting. Said casting comprises a vertical side plate 640, to which the wear plate is secured, and a web 641 extending between said side plate and the main body of the filling head casting, see Figs. 1, 6, 7, and 19. The wear plate is countersunk into the outer face of plate 640 and slides against the vertical face 642 of the crown delivery casting. Preferably the vertical member 559 of the crown delivery casting against which the wear plate slides is dove-tailed in cross section and the side plate 640 of the filling head casting is formed with an undercut flange 643 at its rear edge which slides against one edge of the dove-tailed vertical member 559 of the crown delivery casting, and an undercut strip 64^a is bolted to the front edge of the outer face of plate 640 by bolts 64^b extending through slots 64^c in said plate, the edge of said strip or gib engaging and sliding against the adjacent undercut edge of said vertical member 559 of the crown delivery casting. By reason of the slots 64^c the gib or strip may be snugly adjusted against said vertical member 559.

In order that the main and auxiliary slides may travel together in their normal relation, i. e., that in which the auxiliary slide is lowered with respect to the main slide, when not forced to assume a different relation by the cam cylinder, I have provided a yielding or impositive lock between the two. This lock is best shown in Figs. 6, 7, 32, and 34. The frame of the main slide casting is bored at 650 for the reception of a dog 651 having a wedge-shaped nose 652 for engagement with a notch 653 formed in a block 660 carried by the auxiliary slide to be presently described. The rear end of dog 651 is chambered at 654 to receive a coil spring 655 which is under compression between the bottom of the chamber and a screw plug 656 closing the bore in the slide. The dog is prevented from turn-

ing by the engagement of a screw pin 658 with a groove 657 therein. The auxiliary slide casting is formed with a dove-tailed groove 659 in which is adjustably mounted said block 660 in the face of which adjacent 5 the dog is formed the notch 653 above mentioned. The block 660 may be vertically adjusted in the groove by means of screw bolts 661 and 662 engaging the upper and lower 10 ends respectively of said block and extending through and threaded in lugs 664, 665 upon the auxiliary slide casting. The spring 655 is of such strength as to normally maintain the nose of the dog in the notch or recess 15 and when the parts are in this relation the slides are accurately held in their normal position with respect to each other. When, however, the cam cylinder, above described, 20 operates to move the slides relatively to each other, the dog is forced back and the nose thereof leaves the notch until the normal relation of the slide is substantially restored by the cam cylinder.

Preferably the machine is provided with a 25 cover 680 hinged to casting 554 at 681 and 682 for shielding certain of the moving parts. A latch 684 is pivoted at 685 to the crown delivery casting to engage a catch 686 on the cover to maintain the latter closed.

30 In connection with the description of the filling head I have mentioned the inlet passage 205 thereof by which the carbonated water enters the head on its way to the bottles to be filled. The said passage is connected by a short section of pipe 690, Figs. 6 and 10, and a flexible hose 691, Fig. 1, with a valve fitting 692 on top of a reservoir 693 for the charged water. Said reservoir, see 35 Figs. 44, 45, is provided, in the bottom thereof with a coupling 695 for connection to a carbonater or other suitable source of carbonated water and an inner tube 696 extends upward a short distance from said coupling into the reservoir. An outlet pipe 697 leads 40 from a point adjacent the bottom of the reservoir to said valve fitting 692 upon the top thereof, a turning plug 698 being included in said connection. The fitting 692 includes an inlet chamber 699 into which the outlet 45 pipe leads and an outlet chamber 700 to which the flexible hose above mentioned is connected. There is a valve seat 701 between the inlet and outlet chambers of the fitting with which a downwardly opening valve 702 cooperates. A valve rod 703 extends through a stuffing box 704 and is coupled at 705 to an operating rod or link 706 which is pivoted at 707 to an arm 708 projecting from the clutch operating yoke 296, 50 heretofore described, see also Figs. 1 and 9. The construction is such that when the clutch is opened by the final movement of the main slide, as previously described, the movement of the yoke also opens the valve 702 to permit the charged water to flow to the filling

head. The lower end of the valve rod is enlarged as at 708 and enters a dash pot 709 formed in the fitting casting, there being a small release passage 710 through the enlarged portion of the valve rod. 70

In order to maintain a substantially constant level in the reservoir notwithstanding the release of gas from the water therein, I provide an outlet 711 for the excess gas. This outlet is connected to a screw plug 712 75 screwed into a hollow boss 713 in the top of the reservoir. The plug 712 has an axial passage 714 therethrough which communicates with the outlet 711. The lower end of the plug is reduced and threaded at 715 and a washer 716 is held on the end thereof by a flanged sleeve 717. A float valve 718 cooperates with the washer 716 to close the opening therethrough. Said valve includes the float 719 and a fluted stem 720 extending through the axial bore of the plug, the groove or fluting 721 thereof affording communication between the opening through the washer and the outlet 711. The upper end of the stem 720 is threaded at 722 and provided with an adjustable nut 723 and a lock nut 724. An arm 725 is pivoted to a web 726 of the valve fitting and embraces the valve stem 720 and rests upon the nut 723. Beyond the valve stem the arm is provided with an adjustable weight 727. If excess gas tends to accumulate in the upper end of the cylinder it forces down the liquid level, and the valve opens sufficiently to restore the desired level. 95

100 The apparatus for supplying crowns to the crown delivery mechanism is best seen in Figs. 1, 2, 4, 5, and Figs. 37 to 43 inclusive. It includes a hopper into which the crowns are dumped, a chute or channel leading therefrom to the crown channel of the delivery mechanism with intermediate means by which the crowns are prevented from reaching the chute in other than the proper position to reach the delivery mechanism hollow side down, as is essential for the application thereof to the bottles. 105

110 As best seen in Figs. 1 and 37, a housing 730 which contains a selecting wheel 731 is secured to the head of the adjustable standard at 732. The housing comprises an approximately circular backwall and an annular forwardly projecting flange 733 which surrounds the periphery of the selecting wheel 731. The selecting wheel is journaled upon a central forwardly projecting boss 734 and is peripherally toothed as at 735. As best seen in Figs. 38, 39, the pinion 736 on the reduced end 737 of the shaft 284 (herefore mentioned as the shaft on which worm 283 is mounted) is in mesh with the toothed periphery of the selecting wheel. Pinion 736 is so journaled on shaft 737 that it normally revolves therewith and drives the selecting wheel, but in case of abnormal resistance to revolution by the selecting wheel, 115 120 125 130

as, for example, if it becomes jammed, the pinion permits the revolution of shaft 284. For this purpose pinion 736 is pressed against the annular shoulder 738 formed by the reduction of the end 737 of shaft 284 by a coiled spring 739 interposed and under compression between the front face of pinion 736 and nut 740 on the end of the shaft. The housing is formed with an enlargement 741 which partially surrounds the pinion and shaft 284 extends through the backwall of the housing at 742.

The hopper casting comprises the hopper proper 743 and a partially conical apron or extension 744, the edge 745 of which registers with the flange 733 of the housing. For the greater portion of its periphery the edge of the apron is chamfered as at 746 and extends into the housing as at 747 there being just enough clearance between the edge of the apron and the selecting wheel to permit the free revolution of the latter. The hopper casting is pivoted at 748 to the housing so that when desired it may be swung out forwardly and upwardly away from the housing to permit access to the selector wheel. A spring catch 749 on the hopper casting serves to normally hold the latter in operative position with respect to the housing. A supplemental casting 750, best seen in Figs. 37 and 40 is secured within the apron, the circular flange 751 thereof being screwed to the hopper casting at 752. The supplemental casting comprises a partially frusto-conical member 753 which is flared at 754 and forms in effect a continuation of the hopper through which the crowns pass to the selecting wheel. The frusto-conical portion of the supplemental casting is open at the top as at 755, the ends of the wall thereof merging into vertical walls 756.

A thimble 757 is secured within the hub 758 of the selecting wheel and when the parts are assembled surrounds the bearing boss 734. A stirrer wire 759 secured at one end in the crown of the thimble at 760, is formed into a spiral and terminates in a hook portion 761 within the flaring outlet end of the supplemental casting.

The front face of the selector wheel is formed with a marginal plane portion 762 and a central plane portion 763, the plane of the latter being slightly forward of the plane of the former. Between such plane portions is a shallow groove 764 the outer wall 765 of which is abrupt and the inner wall 766 of which is frusto-conical as best seen in Figs. 37, 38. The rear face of the flange 751 of the supplemental casting is so spaced from the selecting wheel that a crown may enter edgewise between the peripheral plane portion 762 of the wheel and said flange. In other words, the distance between the two plane portions is slightly greater than the height of a crown. The dis-

tance between the outer wall and the edge of the inner wall of the selecting groove is slightly less than the diameter of the open end of a crown, and the abrupt outer wall 765 of the selecting groove is of such diameter and the parts are so designed and arranged that any crown sliding down the flaring opening of the supplemental casting, hollow side up or rearward, is arrested because the edge of the skirt thereof projects into the groove 75 and is caught by the abrupt outer wall of the groove as seen in dotted lines in Fig. 37A. It cannot be released from the wall by being tilted upward into a vertical plane for the reason that the upper edge of the skirt would engage the edge of the inner wall of the groove. On the other hand, any crown which arrives hollow side down at the selecting wheel, its convex surface being against the wheel, as shown in full lines in the same figure, is not arrested by the outer wall of the selecting groove but tilts into a vertical plane and enters the channel between the flange of the supplemental casting and the peripheral plane portion of the selecting wheel. It will be understood that the agitator and the wheel are constantly revolved and the agitator or the other crowns carried thereby pick up any crown arrested in the manner described by the selecting groove and carry it upward until it falls away from the wheel onto and is mingled with the other crowns remaining in the hopper. For the major portion of its periphery the outer wall of the crown channel or pocket between the selector wheel and the flange of the supplemental casting is formed by the cylindrical inner face 770 of the portion 747 of the apron rim which projects into the wheel housing. The extent of said portion is seen in Fig. 38 where it is shown in section. Between the line 771 and the tangential inner surface 772 of said portion, the rim of the apron is cut away to the plane of the face 773 of the flange of casting 750. Throughout a corresponding area the edge of the housing flange is cut back or recessed to the plane of the plane peripheral face of the selector wheel as at 774, Fig. 39. There is thus formed about the crown channel or pocket between the lines 771 and 772 an opening between the housing and the hopper casting of the same width as said pocket. The lower portion of the opening constitutes a passage for the escape of properly turned crowns from the pocket to the crown chute to be presently described. The upper portion of the opening is filled however by a sorting plate 775 which is screwed to the wheel housing casting. The inner edge 776 of the sorting plate is concentric with the outer wall 770 of the annular crown pocket. The lower end edge 777 of the sorting plate is approximately parallel to the tangential portion 772 of the peripheral wall of the crown pocket 130

and spaced therefrom a proper distance to permit properly faced crowns to pass between the two. Both said edges of the sorting plate are rabbeted, at 778 and 779 respectively, toward the hopper casting, the rabbet or recess being of such dimensions and the lower end of the sorting plate being so spaced from the lower wall 772 of the outlet passage for the crowns that a crown in the pocket with its hollow toward the flange of the supplemental casting on arriving at the outlet will pass therethrough the edge of its skirt being received in the rabbet. But a crown faced the other way, on arriving at the outlet is rejected because the distance between the projecting or unrecessed portion of the sorting plate edge and wall 772 is less than the diameter of the edge of the skirt of the crown. The selector wheel turns clockwise, as viewed in Fig. 38 and any crown arriving in the pocket arrives at the exit from the right. If properly faced, it passes out. If, however, an improperly faced crown gets into the pocket, it is rejected by the sorting plate and is carried along up the inner edge thereof by the motion of the spring stirrer and drops back into the mass of crowns against the selector wheel.

The crown chute for delivering crowns from the exit passage of the feeding device just described is or may be cast integral with the wheel housing as to its rear wall 780 and edge walls 781, 782, see Fig. 38, and the channel thereof registers at its lower end with the upper end of the channel heretofore described of the delivery device, the two castings being bolted together at 783, see Figs. 1, 5, 7, 38, 41, 42 and 43. A slotted cover 784 is screwed to the chute casting. The chute is also provided with sorting means to prevent an improperly faced crown reaching the delivery device. With this in view, the rear wall of the chute is formed with an opening 785 of the full width of the channel, see Fig. 41, the lower edge 786 of which is curved and slopes downwardly away from the channel. On either side of the opening the edge walls of the chute are cut away for the insertion of blocks 787, 788 having projecting guides 789, 790 on their inner faces. The guides are so formed as to permit a properly faced crown to pass between them, the skirts of such crowns entering the recesses between the guides and the cover. The rear edges of the guides are so formed at 791 however as to engage the edge of the skirt of an improperly faced crown and divert it through the opening and out of the chute.

The syruper, or apparatus for charging a definite amount of syrup or flavoring matter in each bottle prior to charging the bottle with carbonated water, will now be described more particularly with reference to Figs. 1, 3, 4, and 56 to 64 inclusive. As shown in Fig. 1, the syruper is mounted on

the main slide in advance of the filling head so that a bottle in the bottle carrier is first presented beneath the syruper and then with the next step of rotation is carried to filling position beneath the filling head. The 70 syruper comprises a measuring cylinder which receives the charge for each bottle and a vertically reciprocable valve carrier and nozzle which is arrested by the bottle when the syruper descends with the slide, thus 75 automatically opening the discharge valve and closing the inlet valve. A pump or booster is also provided for filling the measuring chamber of the syruper.

The main casting 800 of the syruper is 80 formed with a measuring chamber 801 in which is reciprocable a follower 802. The upper end of the cylinder is closed by a cap 803 threaded thereinto, the joint being sealed at 804 by a packing ring. A sleeve 85 805 extends through the cap and is adjustable therein by means of a threaded engagement 806 therewith. By adjusting the sleeve, which is provided with a handle 807 for the purpose, the upward movement of 90 the follower is limited and thus the charge of the syruper may be determined. The cap 803 is formed with an upwardly extending boss 80^a through which said sleeve extends and said boss is threaded at 808 to 95 receive a clamping nut 809. Said boss is tapered above the threaded portion as at 810 and split as at 811, see Figs. 58 and 61, and the clamping nut above mentioned is formed with an internal taper at 812 which 100 fits over the tapered split end of the boss, so that by screwing the nut down the split members of the boss are forced into close frictional contact with the sleeve to prevent the same from turning. In adjusting the 105 sleeve the clamping nut is loosened and after adjustment the nut is screwed down to clamping position. The follower is provided with a rod 813 which is threaded at 814 into a plug 815, which may be of hard rubber secured in the upper wall of the follower and the rod extends through the upper end of the sleeve and is provided with a knob 816. The rod permits the movement of the follower to be checked. A gland 817 in the 110 upper end of the sleeve and about the rod prevents leakage.

The lower end of the measuring chamber is formed by a transverse wall or septum 818 beneath which is an inlet chamber 819 with which inlet passage 820 communicates, 120 see Fig. 59. The inlet passage is provided with a gate valve 821 which may be of ordinary construction. The inlet chamber communicates with the measuring chamber through passages 822 (see also Fig. 62) through the septum, and about the lower end of said passages is an annular valve seat 823, with which a rubber valve gasket 824 on the valve carrier cooperates. When the 125

valve carrier is arrested by contact of the nozzle 825 therewith with a bottle, as the syruper descends with the main slide, the further descent of the syruper closes the valve gasket against its seat, thus shutting off the inlet chamber from the measuring chamber.

The same relative movement between the valve carrier and the body of the syruper 10 opens the outlet valve for the delivery of syrup to the bottle. The valve seat 826 is cast integral with a hollow stem 827 which is fixed to the septum 818. The septum is formed with a chamber 828 in which is an internal flange or rib 829 with a rabbet 830 beneath said flange. The hollow stem 827 is formed with a flange 82^a which fits into the rabbet, and the stem extends through said flange and chamber 828 and is threaded at 82^b for the reception of a cap nut 82^c, the edge of which is provided with a packing ring 82^d which is compressed between said nut and the upper edge of the wall of chamber. The passage 82^e of the stem communicates with chamber 828 and the latter is open to 25 the outside through passage 831, so that air from the bottle may escape therethrough.

The valve carrier comprises a sleeve 832 near the lower end of which is an inwardly projecting annular rib or flange 833 which forms a seat for a funnel 834, the body of which fits closely within the bore of the sleeve. A gasket valve 835 rests upon the upper edge of the funnel and projects inwardly therefrom and over the edge of the seat 826 with which it cooperates. The gasket is clamped between the upper edge of the funnel and a hollow plug 836 threaded into the upper end of the sleeve and serving also to retain the inlet valve gasket 824, being formed with an annular recess 837 into which said gasket extends. The sleeve is packed in the lower end of the casting at 838 and the lower end of the sleeve is threaded at 839 to receive 40 the nozzle 825 and also receives a rubber gasket 840 for contact with the bottles. A spring 841 normally holds the valve carrier in the position of Fig. 57.

With the construction thus far described, 50 it is obvious that when the syruper moves downwardly and the valve carrier is arrested by the bottle, the parts assume the position of Fig. 58, the inlet valve gasket shuts off the inlet chamber from the measuring chamber and the discharge valve gasket is carried upward from its seat so that the charge of syrup 55 may flow from the measuring chamber through the openings 822, the hollow plug 827, the valve gasket 835, the funnel and into the bottle. It will be noted that the hollow stem 827 extends substantially through the neck of the funnel and is formed with an exterior spiral rib or ribs by which the syrup 60 is given a whirling motion in its exit from the nozzle so that it is projected against the

walls of the bottle. The air expelled from the bottle by the entrance of the syrup flows off through the hollow stem, chamber 828 and passage 831 to the atmosphere.

The follower is hollow, the lower end wall 70 thereof being formed with a hollow internally threaded boss 842 to receive the threaded boss 84^a on a casting 84^b between which and the follower proper is clamped the leather packing 843. The casting is hollowed out at 844 to receive the cap nut 82^c when the follower descends to permit the latter to expel practically all of the liquid in the cylinder.

The descent of the follower in discharging the syruper is assisted and accelerated by air 80 driven from the bottles when the latter are being filled with charged water and which, as heretofore described, escapes through the filling head to the controller housing 371. As heretofore stated, a small proportion of the air from each bottle escapes at the throttle device of the housing in the early stage of filling to the outlet chamber 373 of the housing, and after the filling is completed the pressure is 85 equalized between the inlet and outlet chambers by the dropping of valve 280 from its seat. A nipple 845 communicates with the outlet chamber of the housing and a rubber hose 846 connects said nipple with an elbow 847 screwed into the boss 848 on the upper end 90 of the main syruper casting and communicating with the interior thereof above the follower. (See Figs. 28, 1 and 60). Thus the air from the controller housing exerts its pressure on the upper face of the follower in the 100 syruper and when the outlet valve of the syruper is open, assists in forcing the follower downward to expel the syrup.

In order to substantially restore atmospheric pressure in the upper end of the 105 syruper as well as in the controller housing after the charge of syrup has been expelled, and to drain from the space above the follower any liquid which has come over with the air into the bottle receiving the charge of 110 syrup, I provide a by-pass from the space above the follower to the bottle receiving nozzle and control the by-pass both by the follower and by the nozzle. For this purpose 115 an annular groove 849 is formed in the wall of the chamber at such a level therein that it is uncovered by the follower only when the latter has nearly reached its lowermost position in the expulsion of the syrup. A channel 850 formed in the wall of the syruper 120 communicates with said groove and with a vertical passage 851 likewise formed in the casting (see Figs. 57, 58). The lower end of passage 851 is enlarged at 852 to receive a slide pipe 853, the lower end of which is threaded at 854 into a nipple 855 on the sleeve of the valve carrier. The nipple 125 communicates with the interior of the sleeve. The bore 856 of the sliding pipe terminates short of the upper end there- 130

of and communicates with a lateral bore 857. A stuffing box 858 prevents leakage about the sliding pipe. An enlarged chamber 859 is formed intermediate channel 851. In the normal condition of the apparatus the slide pipe is in the position shown in Fig. 57, in which the lateral passage 857 thereinto is closed. When, however, the syruper descends and the valve carrier is stopped by a bottle, the slide rod is raised with respect to the syruper body and communicates with the chamber 859 which is in communication with the syruper chamber through passages 850, and 851 except insofar as communication is cut off by the follower. As the follower descends under the pressure of the air above it and reaches approximately its lowermost position, it uncovers the groove 849 and the surplus air and any liquid above the follower and in the controller housing escapes through passages 850, 851, the slide pipe and the nozzle, into the bottle beneath the latter. Thus atmospheric pressure is restored above the follower and in the controller.

The syruper is so mounted on the main slide of the machine as to be readily removed therefrom for cleaning, repairing, etc., and at the same time it is adapted to yield upwardly in its holder so that the nozzle will always be properly elevated with respect to the syruper when the latter descends and at the same time there will be no danger of breakage of the bottles. Referring more particularly to Figs. 56 and 57, it will be seen that the holder for the syruper comprises a main casting 860 and an auxiliary casting 861, the two castings together forming a sleeve for the reception of the syruper. The edges of the main casting are formed with perforated upper and lower lugs 862, 863, and those of the auxiliary casting with intermediate lugs 864, see Fig. 63, and pins 865, 866 are inserted through the openings therein to hold the castings in proper relation. The lower ends of the pins are preferably formed with annular grooves 867 for locking them by means of keys 868, see particularly Fig. 63.

The syruper is formed adjacent its upper end as at 869 with an outwardly extending annular flange adapted to rest upon the upper end of the sleeve or holder, a cushion or washer 870 being interposed between the flange and sleeve. Adjacent its lower end the main casting of the syruper is formed with approximately opposite lugs 871 which are perforated at 872 for the reception of pins 873. Each pin is formed with a button 874 on its upper end between which button and lug 871 is compressed a coil spring 875 surrounding the pin. Beneath the lug 871 the pin receives a washer 876 which resists the upward pressure of the spring and is held in place by pin 877. The main casting of the holder is formed with an inwardly extending

web 878 which forms an abutment against which buttons 874 of the rods are pressed by the springs on said rod. Except for the resistance of the two springs just mentioned, the syruper is free to rise or slide vertically in the holder sleeve. Therefore when the syruper descends upon a bottle of more than minimum height, after the valve carrier has risen with reference to the syruper a sufficient distance to close the inlet valve against the seat preventing the further descent of the syruper, the springs 875 permit the syruper to rise slightly with reference to the holder.

The main casting of the holder is formed with a sleeve 879 connected to the main body thereof by webs 880, 881, see Figs. 9, 56, 57. The main slide is formed with perforated lugs 882, 883, so spaced as to admit between them said sleeve or barrel 879 on the syruper holder. When the syruper is assembled with the machine, sleeve 879 is inserted between said lugs and a pin 884 is thrust through the lugs and barrel to secure the parts in proper relation, washers 885 and pins 886 holding pin 884 in place. In order to prevent the syruper swinging about pin 884, a lug 887 is formed on said barrel and is perforated at 888 to receive a bolt 889 extending through lugs 890—890 on the main slide.

The syruper receives syrup from a tank, not shown, preferably located above the machine, through a pump or booster 891 mounted on the adjustable standards of the machine above and to one side of the syruper, see Figs. 1, 64 and 65. The cylinder of the pump is formed with a flange 892 by which the pump is secured to the adjustable standard of the machine. The upper cap 893 of the pump cylinder is formed with an inlet passage 894 having a valve seat 895 with which a spring actuated valve 896 cooperates. A flexible tube 897 connects such inlet passage with the syrup supply tank. A hollow piston 898 having a ball valve 899 and a hollow piston rod 900 operates in the pump cylinder. A spring 901 intermediate the lower head 902 of the pump cylinder and said piston acts to return the latter to its upper position, and is assisted by an auxiliary spring 903 connected to brackets 904, 905 on the hollow piston rod and cylinder, respectively. The hollow piston rod is formed, outside the cylinder, with a threaded nipple 906, the bore of which communicates with the hollow of said piston rod and said nipple is connected by a flexible tube 907 with the intake valve casing 821 of the syruper, see Figs. 1 and 59. Below nipple 906 the piston rod is solid as at 908 and is longitudinally grooved at 909 and threaded at 910. As best seen in Fig. 9, the solid portion of the piston rod extends through an eye 911 in the bracket 882 of the main slide, and is provided with a collar 912 and lock nuts 913. The collar on the piston rod engages the

under surface of the bracket 882 and thus when the main slide descends it draws down the piston rod and the piston of the syrup pump or booster, and when the slide ascends and relieves the pressure on the collar the piston rod and piston are forced upwardly by the springs above mentioned. A screw pin 914 extends through the bracket into the groove in the piston rod and thus prevents the latter from turning.

At every down stroke of the piston, the syrup flows into the cylinder. On the up stroke of the piston the syrup flows past the ball valve thereof and into the hollow piston rod, through the flexible tube and into the syruper below the follower therein, and the follower is raised until stopped by the adjusted screw sleeve 805, thus permitting a definite predetermined charge to enter the syruper. At this time the valve carrier is in the lowered position with respect to the body of the syruper as shown in Fig. 57, the inlet chamber of the syruper being open to the measuring chamber. At the same time the outlet valve of the syruper is closed. When the syruper descends it carries with it the valve carrier until the descent of the latter is arrested by the bottle to be charged. The syruper continues its descent, thus opening the discharge valve and closing the inlet valve. As heretofore pointed out, if the particular bottle being filled is of more than the minimum height, the continued descent of the main slide after the inlet valve of the syruper is closed merely causes the syruper to rise a little in the sleeve or holder therefor. With the opening of the outlet valve in the syruper the follower begins its descent under pressure of the air supplied above it as previously described, and the descent continues until all of the syrup in the measuring chamber escapes therefrom. But as the upper face of the follower uncovers the groove 849 in its cylinder, the sliding pipe 853 at this time being in the upper position shown in Fig. 58, any liquid in the cylinder above the follower and the surplus air therein escape, when the main slide ascends carrying with it the syruper, the outlet valve closes and the inlet valve opens and the operation of the pump or booster again supplies the syruper with a charge of syrup.

Instead of the bottle carrier described above having closed bottle receiving openings in which the bottles are placed by hand, the machine may be constructed with a bottle carrier having open pockets or seats into which the bottles are automatically fed by a conveyor, as shown in Figs. 53 to 55 inclusive, the machine being otherwise constructed as above described. Referring to Figs. 53 to 55, the frame 100' of the automatically fed machine comprises a table top 101' having a downwardly extending boss 103' in which the upper end of the shaft 104' is journaled.

The lower end of said shaft is journaled in a bearing 920 cast with the frame. On the lower end of the shaft is mounted a pinion 138' driven like pinion 138 of the hand fed machine from the main shaft through gearing which may be similar in all respects to the gearing shown in Fig. 48 in connection with the hand fed machine. A member of such gearing is shown at 134' in Fig. 54. Intermediate bearings 103' and 920 a sleeve 75 921 is revolvably mounted upon shaft 104', which sleeve at its lower end, as at 922, carries a sprocket and at its upper end is formed with a bevel gear 923. As best seen in Fig. 55 a sprocket chain 924 engages said sprocket 80 and a second sprocket mounted on the main shaft. Thus the sleeve 921 is driven from the main shaft independently of the shaft 104'.

An extension 926 is secured to the frame 85 at one side, the top 927 of which is in the same plane with the table top 101'. The extension is formed with downwardly extending bearing brackets 928, 929 in which a shaft 930 is journaled, said shaft having on one end a bevel gear 931 meshing with bevel gear 923 above mentioned and on the other end a bevel gear 932. The latter gear is in mesh with a bevel pinion 933 on a shaft 934 journaled at its end in the downwardly extending walls of the extension. Three, or it may be more, sprocket wheels 935 are mounted together upon shaft 934 and revolve therewith. On the other side of the table an extension 936 is secured thereto in which extension is journaled a shaft 937 carrying an idler wheel 938 in the periphery of which are formed grooves 939 corresponding in number and spacing to the sprockets 935. Sprocket chains 940 extend about said sprocket and the grooved idler and travel over the table top, including the top of said extensions in a shallow groove of proper width to receive the same and are of such depth that the upper edges of the same are 100 in the plane of the table top.

The bottle carrier b' is a casting comprising an intermediate barrel 941 and outwardly extending flanges 942, 943 formed as star wheels having peripheral recesses 944 into which the bottles are successively fed by the multiple sprocket chain construction above described.

Suitable guides are provided for maintaining the bottles in the proper path on the chain and in the revoluble bottle carrier. These guides include an adjustable stationary guide 945 bolted to the table at 946 in front of the chain with a supplemental guide member 947 secured thereto and extending over the chain to direct the incoming bottles to the seats in the star wheel. The latter is so driven from the main shaft by the connections above described that, intermediate successive operations of the filling head, it advances a step 120 125 130

or fraction of a rotation to present one of its bottle receiving seats or recesses over the bottle support beneath the filling head, and at the same time bring the bottle in the next seat or recess beneath the syruper and present the third recess or seat in position to receive a bottle from the traveling sprocket chain.

On the rear side of the chain and adjacent to the entering end of the bottle way is a stationary guide 948. A movable guide 949 is connected to said stationary guide by a pin 950 extending into a slot 951 in said stationary guide. The guide 949 is pressed to the right, as seen in Fig. 53, by a spring 952 surrounding a bolt 953 which is pivoted on pin 950, the spring being compressed between an abutment on said bolt and an adjustable abutment 954 on the stationary guide. To the right hand end of the movable guide 949, at 955, is linked a movable guide 956 to the other end of which is pivoted a guide 957 adjustably mounted on the table by bolts 958. To the left-hand end of guide 957, at 959 is pivoted a guide 960 having a rearwardly extending arm 961. A bolt 962 is pivoted to said arm 961 and extends through a perforated ear 963 on the guide 957, a spring 964 being compressed between shoulder 965 on said bolt and an adjustable sleeve 966 threaded into said lug. Lock nuts 967 prevent the bolt from leaving said sleeve.

The guides 949 and 956 by reason of the structure described yield when necessary to bottles being carried from the chain by the star wheel to the syruping position but maintain a suitable pressure thereon to hold them in the recesses or seats of the carrier. The guide 960 under pressure of its spring above described, maintains pressure on a bottle in its seat in the star wheel, passing from the syruping to the filling position and while in the latter position so that it is accurately positioned beneath the filling head. Stationary guides 969 and 970 guide the bottle as it is being returned from the filling position to the chain belt and from the latter onto the extension 926.

The bottles are fed by hand or otherwise to the chain with sufficient rapidity so that there is always a bottle ready to enter a recess in the star wheel when presented, the chain slipping beneath the bottles when the latter are arrested. As each bottle seat of the carrier is presented a bottle is carried into it, being guided by the guides above described. On the next step of rotation of the bottle carrier or star wheel, the bottle is carried to the syruping position, being held in the carrier seat by the spring pressed guides above described. At the next feeding movement of the star wheel the bottle is carried to the filling position and the next movement of the star wheel carries it away from the filling position and finally it is moved onto the chain

at the right hand side of the machine as seen in Fig. 53 by which chain it is carried onto the extension table 927.

Manifestly other forms of machines or devices may be used to present the bottles to be filled to the filling head, the bottles may be separately charged with syrup or other forms of syrups may be used and other means be provided for feeding the crowns to the device by which they are placed in the filling head. Other modifications of the machine which are well within the scope of the invention will suggest themselves to the skilled mechanic and it is to be understood that in the following claims I have endeavored to cover the invention as broadly as the prior state of the art will permit.

I claim:

1. In a machine of the class described, a bottle support, a vertically movable filling head, means for lowering the filling head into engagement with the bottle to be filled and raising it therefrom, means for stopping the first-mentioned means during the filling of a bottle, and means operated by air driven out of the bottle during the filling thereof for again starting the filling head lowering and raising means after the filling of the bottle is completed.

2. In a machine of the class described, a bottle support, a vertically movable filling head, means for lowering the filling head into engagement with the bottle and raising it therefrom means operated by the engagement of the filling head with a bottle for arresting the movement of the lowering and raising means while the bottle is being filled.

3. In a machine of the class described, a bottle support, a vertically movable filling head thereover, means for lowering and raising the filling head, means for stopping the last said means during the filling of a bottle and means operated by the air driven out of a bottle for restoring movement of the lowering and raising means.

4. In a machine of the class described, a bottle support, a filling head above the same, means for effecting relative vertical movement between the bottle support and filling head, a pneumatic motor, connections between the filling head and motor whereby the air escaping from a bottle during the filling operation actuates the motor and connections between the motor and said means for effecting relative movement between the bottle support and filling head whereby said means is set in motion.

5. In a machine of the class described, a bottle support, a filling head mounted above said bottle support and vertically movable toward and from the latter, means for raising and lowering the filling head, a source of power for driving said means, a clutch intermediate said source of power and said means, means for opening the clutch, a pneumatic

motor, connections between said motor and filling head whereby the motor is operated by air escaping from the bottle being filled through said filling head, means operated by said motor to release the clutch from said clutch-opening means, and means to close the clutch.

6. In a machine of the class described, a bottle support, a filling head mounted above said bottle support and vertically movable toward and from the latter, means for raising and lowering the filling head, a source of power for driving said means, a clutch intermediate said source of power and said means, means for opening the clutch operated by the descent of the filling head to the filling position, a pneumatic motor, connections between said motor and filling head whereby the motor is operated by air escaping from a bottle being filled through said filling head, means operated by said motor to release the clutch from the clutch-opening means, and means for closing the clutch.

7. In a machine of the class described, a bottle-support, a filling head mounted above said support and vertically movable with relation to the latter, a shaft, a cam on said shaft, connections between the cam and filling head for raising and lowering the latter, means for driving the shaft, a clutch intermediate said shaft and driving means, comprising a member fixed to the shaft and an axially movable element, means for moving the last named element to close the clutch, and means movable with the filling head for opening the clutch.

8. In a machine of the class described, a bottle-support, a filling head mounted above said bottle support and vertically movable relative thereto, a shaft, a cam on the shaft, connections between the cam and filling head for raising and lowering the latter, means for driving the shaft, a clutch intermediate said shaft and said driving means, comprising a member fixed on the shaft and a member axially movable relative thereto, means for closing the clutch, means movable with the filling head for opening the clutch, and means for disengaging the last mentioned means when the filling of a bottle is completed.

9. In a machine of the class described, a bottle support, a filling head mounted above said bottle support and vertically movable relative thereto, a shaft, a cam on the shaft, connections between the cam and filling head for raising and lowering the latter, means for driving the shaft, a clutch intermediate said shaft and said driving means, comprising an element fixed on the shaft and an element axially movable relative thereto, means for closing the clutch, means movable with the filling head adapted to engage and shift the movable element of the clutch for opening the same, a pneumatic motor, means for closing the clutch controlled

thereby, and connections between said motor and filling head whereby air driven out of the bottle during the filling operation controls the operation of the motor.

10. In a machine of the class described, a bottle support, a filling head mounted above said bottle support and vertically movable relative thereto, a shaft, a cam on the shaft, connections between the cam and filling head for raising and lowering the latter, means for driving the shaft, a clutch intermediate said shaft and said driving means comprising a member fast on said shaft and a member movable relatively thereto, means movable with the filling head and also movable with respect thereto into and out of a position to engage the movable member of the clutch, a cam device for moving the last mentioned means into engaging position when the filling head descends to filling position, and trip mechanism for releasing the last mentioned means when a bottle is filled.

11. In a machine of the class described, a bottle support, a vertically movable slide above the same, a filling head carried by the slide, a cam, connections between the cam and slide for reciprocating the latter, a shaft on which the cam is mounted, driving means for the shaft, a clutch on the shaft and intermediate the same and the driving means, said clutch comprising a movable element, means for shifting said movable element to close the clutch, and means for opening the clutch comprising a pivoted member engaging the movable element of the clutch, a catch mounted on the slide and movable thereon into and out of position to engage said pivoted member, means for moving the catch into engaging position as the slide descends, said catch engaging the pivoted member when the slide is completing its descent and swinging it to open the clutch, and means for tripping the catch to release the pivoted member when the filling of a bottle is completed.

12. A machine as set forth in claim 8 in which the means for disengaging the clutch opening-means comprises a pneumatic motor, connections between the same and the filling head whereby the air discharged from the bottle is led to the motor to operate the latter.

13. In a machine of the class described, a bottle support, a filling head over the bottle support, a vertically reciprocable slide on which the filling head is carried, a vertical shaft, a cam thereon for reciprocating said slide, means for driving the shaft, a clutch intermediate the shaft and driving means comprising two elements one of which is axially movable on the shaft, means yieldingly holding said element in engagement with the other element of the clutch, clutch opening means engaging the movable element of the clutch for withdrawing it from

engagement with the other element thereof, a catch mounted on the slide, and movable into and out of position to engage the clutch opening means to open the clutch on the descent of the slide, means to move the catch into engaging position, and means to trip the catch to release the clutch when the filling of a bottle is completed.

14. In a machine of the class described, a bottle support, a filling head, a vertically movable slide carrying the filling head, a vertical shaft, a cam thereon for reciprocating said slide, means for driving the shaft, a clutch intermediate the shaft and driving means comprising two elements one of which is axially movable on the shaft, means normally holding said element in engagement with the other element of the clutch, clutch-opening means engaging said movable element, a catch mounted on the slide adapted to engage the clutch opening means when the slide is lowered and movable toward and from the clutch opening means, a carrier on which the catch is pivoted, means for moving the carrier for positioning the catch to engage the clutch opening means on the descent of the slide and means to trip the catch to release the clutch-opening means when the filling of a bottle is completed.

15. In a machine of the class described, a bottle support, a filling head, a slide vertically guided, and on which the filling head is carried, a vertical shaft, a cam thereon for reciprocating said slide, means for driving the shaft, a clutch intermediate the shaft and driving means comprising two elements one of which is axially movable on the shaft, means normally holding said element in engagement with the other element of the clutch, a yoke engaging the movable element of the clutch for withdrawing it from engagement with the other element thereof, a catch movably mounted on the slide, means for positioning the catch to engage the yoke on the descent of the slide, a pneumatic motor, connections between the motor and filling head for conveying the air discharged from a bottle to the motor whereby the motor is actuated by air driven from the bottle when the latter is filled, and means operated by the motor to release the catch from the yoke when the filling of a bottle is completed.

16. In a machine of the class described, a bottle support, a filling head, a slide vertically guided, and on which the filling head is carried, a vertical shaft, a cam thereon for reciprocating said slide, means for driving the shaft, a clutch intermediate the shaft and driving means, comprising two elements one of which is axially movable, means normally holding said movable element in engagement with the other element of the clutch, a pivoted yoke engaging the movable element of the clutch for withdrawing it from engagement with the other element thereof, a catch piv-

otally mounted on the slide and movable into and out of engaging position with respect to the yoke, means for moving the catch into engaging position and means for tripping the catch to release the yoke when a bottle is filled.

17. In a machine of the class described, a bottle support, a main slide, an auxiliary slide, a filling head on the auxiliary slide, a cam cylinder, means intermediate the cam cylinder and said slides for reciprocating the latter, a shaft on which the cam cylinder is mounted, means for revolving the shaft, a clutch intermediate said means and shaft, comprising an axially movable member, means for moving said member to close the clutch, a yoke engaging said member for opening the clutch, a catch carried by the main slide and movable thereon into and out of position to engage the yoke, a cam on the auxiliary slide, and means connected to the catch and engaged by said cam whereby the catch is thrown into position to engage the yoke when the main slide moves downward relatively to the auxiliary slide, and means to trip the catch to release the yoke.

18. A machine as set forth in claim 8 in which the means for disengaging the clutch opening means comprises a pneumatic motor, a device operated thereby engaging the catch to disengage it from said pivoted member, connections from the filling head to said motor for supplying air from a bottle being filled to the motor to operate the latter and a controller in said connections having a passage for the escape of air and means to throttle said passage as the pressure in the controller rises.

19. In a machine of the class described, a bottle support, a filling head, a vertically movable slide on which the filling head is mounted, means for reciprocating the slide, driving means, a clutch between said reciprocating means and driving means, comprising a relatively movable member, yielding means for normally holding said relatively movable member of the clutch in engagement with the other member thereof, clutch opening means, a second vertically movable slide, a catch on the latter movable into engaging and non-engaging positions in respect to the clutch opening means, means on the first slide for moving the catch into engaging position and means on the second said slide for releasing the catch from the clutch opening means.

20. In a machine of the class described, a bottle support, a filling head, a vertically reciprocable main slide, an auxiliary slide on which the filling head is carried, means for reciprocating said slides, a driving means, a clutch between the reciprocating and driving means including a relatively movable element, clutch opening means engaging said relatively movable element, a catch on the main slide movable into and out of position

to engage the clutch opening means, means on the main slide for moving said catch into engaging position and means on the auxiliary slide for actuating the last-mentioned means.

21. In a machine of the class described, a bottle support, a filling head, a vertically reciprocable main slide, an auxiliary slide on which the filling head is carried, means for reciprocating said slides, a driving means, a clutch between the reciprocating means and the driving means, including a relatively movable element, clutch opening means for disengaging said movable element from the other element of the clutch, a catch movable into and out of position to engage the clutch opening means, a carrier pivoted to the main slide and carrying said catch, means on the main slide for swinging said carrier to carry the catch into engaging position, and means on the auxiliary slide for actuating the last mentioned means.

22. In a machine of the class described, a bottle support, a filling head, a vertically reciprocable main slide, an auxiliary slide on which the filling head is carried, means for reciprocating said slides, a driving means, a clutch between the reciprocating and driving means including a relatively movable element, clutch opening means for disengaging said element from the other element of the clutch, a catch on the main slide movable into and out of position to engage the clutch opening means, a carrier pivoted to the main slide and carrying said catch, an arm on the carrier, a lever on the main slide, a link connecting the arm and lever, and a cam on the auxiliary slide for engaging and operating the lever to move the catch to engaging position.

23. In a machine of the class described, a bottle support, a filling head, a vertically reciprocable main slide, an auxiliary slide on which the filling head is carried, means for reciprocating said slides, a driving means, a clutch between the reciprocating and driving means including a relatively movable element, clutch opening means for disengaging said element from the other element of the clutch, a carrier pivoted on the main slide, means intermediate the carrier and auxiliary slide for swinging said carrier toward the clutch opening means when the main slide moves downward relatively to the auxiliary slide, a catch pivoted on said carrier and movable into and out of position to engage the clutch opening means and trip mechanism engaging the catch and movable to release the same from the clutch opening means when the bottle is filled.

24. In a machine of the class described, a bottle support, a filling head, a vertically reciprocable main slide, an auxiliary slide on which the filling head is carried, means for reciprocating said slides, a driving means, a clutch between the reciprocating and driving means including a relatively movable ele-

ment, clutch opening means for disengaging said element from the other element of the clutch, a catch on the main slide movable into and out of position to engage the clutch opening means, means for moving the catch into engaging position, and trip mechanism including a pneumatic motor and a rod connected to the piston thereof and engaging the catch to release the clutch opening means when the motor is actuated.

25. In a machine of the class described, a bottle support, a filling head, a vertically reciprocable main slide, an auxiliary slide on which the filling head is carried, means for reciprocating said slides, a driving means, a clutch between the reciprocating and driving means including a relatively movable element, clutch opening means for disengaging said element from the other element of the clutch, a catch on the main slide movable into and out of position to engage the clutch opening means, means for moving the catch into engaging position, trip mechanism including a pneumatic motor, a rod connected to the piston thereof and engaging the catch to release the clutch opening means when the motor is actuated, and connections between the filling head and motor whereby the air driven out of a bottle being filled actuates the motor.

26. In a machine of the class described, a bottle support, a filling head, a vertically reciprocable main slide, an auxiliary slide on which the filling head is carried, means for reciprocating said slides, a driving means, a clutch between the reciprocating and driving means including a relatively movable element, clutch opening means for disengaging said element from the other element of the clutch, a catch on the main slide movable into and out of position to engage the clutch opening means, means for moving the catch into engaging position, trip mechanism for releasing the catch from the clutch opening means comprising a pneumatic cylinder, a connection from said cylinder to the filling head whereby the air escaping from the bottle through the filling head during the filling operation enters said cylinder, a piston in said cylinder and a rod carried thereby and engaging the catch to trip the latter.

27. In a machine of the class described, a bottle support, a filling head, a slide on which the filling head is carried, means for reciprocating said slide, a driving means, a clutch between the reciprocating and driving means, including a relatively movable element, clutch opening means for disengaging said element from the other element of the clutch, a catch movable into and out of position to engage the clutch opening means, a carrier on which the catch is pivoted, the carrier being pivoted on the slide and movable toward and from the clutch opening means, means for swinging the carrier into and out

of position in which the catch may engage the clutch opening means, a pneumatic cylinder carried by the slide, connections whereby the cylinder receives air driven out of a bottle during the filling operation, a piston in said cylinder, a rod connected to the piston and adapted to engage and trip the catch when the cylinder receives air, a spring in the cylinder resisting the movement of the piston, an abutment movable in said cylinder between which and the piston the spring is compressed, means for adjusting the position of said abutment in accordance with the pressure on the liquid being filled into the bottle comprising a second cylinder connected to a chamber containing liquid being filled, a piston in said cylinder and connections between the last said piston and said abutment.

28. In a machine of the class described, a bottle support, a filling head, a vertically reciprocating slide carrying said filling head, means for reciprocating said slide, a driving means, a clutch between the reciprocating and driving means including a relatively movable element, clutch opening means for disengaging said element from the other element of the clutch, a catch so mounted on the slide as to be movable into and out of position to engage the clutch opening means when the slide descends, means for tripping the slide comprising a pneumatic motor and a rod connected to the piston thereof and engaging the catch to release the clutch opening means when the motor is actuated, connections between the filling head and motor whereby the air driven out of a bottle being filled actuates the motor, a controller in said connection having an air-receiving chamber and an air escape passage therefrom, and means operated by the pressure of air for closing said air escape passage as the pressure in the controller rises.

29. In a machine of the class described, a bottle support, a filling head, a vertically reciprocable slide, carrying the filling head, means for reciprocating said slide, a driving means, a clutch between the reciprocating and driving means including a relatively movable element, clutch opening means for disengaging said element from the other element of the clutch, a catch carried by the slide and movable thereon into and out of position to engage the clutch opening means when the slide descends, a pneumatic motor and means operated thereby for tripping the catch, a housing comprising a chamber connected to the filling head and receiving air from the latter when a bottle is being filled, a connection from said chamber to said motor, there being an air escape passage from said chamber, and a throttling device movable under pressure in said chamber to restrict the escape of air therefrom.

30. In a machine of the class described, a

bottle support, a filling head, a vertically reciprocable slide, carrying the filling head, means for reciprocating said slide, a driving means, a clutch between the reciprocating and driving means including a relatively movable element, clutch opening means for disengaging said element from the other element of the clutch, a catch carried by the slide and movable thereon into and out of position to engage the clutch opening means when the slide descends, a pneumatic motor and means operated thereby for tripping the catch, a housing comprising a chamber connected to the filling head and receiving air from the latter when a bottle is being filled, a connection from said chamber to said motor, there being an air escape passage from said chamber, a throttling device movable under pressure in said chamber to restrict the escape of air therefrom, there being a second air escape passage from said chamber, a valve for closing the same and means for closing the valve during the filling operation.

31. In a machine of the class described, a bottle support, a filling head, a vertically reciprocable main slide, an auxiliary slide, mounted on the main slide and on which the filling head is carried, means for reciprocating said slides together and independently of each other, a driving means, a clutch between the reciprocating and driving means, including a relatively movable element, clutch opening means for disengaging said element from the other element of the clutch, a pivoted catch on the main slide movable into and out of position to engage clutch opening means, means for moving the catch into engaging position when the main slide moves downward, means for tripping the catch to release the clutch opening means, comprising a pneumatic motor and a rod connected to the piston thereof, and engaging the catch, a housing having an inlet chamber, connections from said inlet chamber to the filling head, whereby air expelled from a bottle is conducted to said inlet chamber of the housing connections from said inlet chamber to the motor, an outlet chamber in said housing, connections between said inlet and outlet chambers comprising a tapered passage, a throttling device movable longitudinally of said tapered passage, a spring normally forcing the throttling device toward the portion of said passage of larger cross section, a diaphragm exposed to the pressure in said inlet chamber and operating on the throttling device to force it toward the portion of said tapered passage of less cross section.

32. In a machine of the class described, a bottle support, a filling head, a vertically reciprocable slide, carrying the filling head, means for reciprocating said slide, a driving means, a clutch between the reciprocating and driving means including a relatively movable element, clutch opening means for disengag-

ing said element from the other element of the clutch, a catch carried by the slide and movable thereon into and out of position to engage the clutch opening means when the slide descends, a pneumatic motor and means operated thereby for tripping the catch, a housing comprising a chamber connected to the filling head and receiving air from the latter when a bottle is being filled, a connection from said chamber to said motor, there being an air escape passage from said chamber, a throttling device movable under pressure in said chamber to restrict the escape of air therefrom, a second air escape passage from said chamber, a valve for closing the same and means for closing the valve during the filling operation, and a valve on said throttling device for closing said connection between the inlet and outlet chambers.

33. In a machine of the class described a bottle support, a filling head, a vertically reciprocable main slide, an auxiliary slide, on which the filling head is carried, means for reciprocating said slides, a driving means, a clutch between the reciprocating and driving means, including a relatively movable element, a clutch opening means for disengaging said element from the other element of the clutch, a catch on the main slide movable into and out of position to engage the clutch opening means, means on the main slide and engaged by the auxiliary slide for moving said catch into position to engage the clutch opening means when the main slide moves downwardly with respect to the auxiliary slide, trip mechanism for releasing the catch from the clutch opening means comprising a pneumatic motor and a rod connected to the piston thereof and engaging the clutch, a housing having a chamber therein, connections from said chamber to the filling head, whereby air driven out of a bottle being filled enters said chamber, a connection from said chamber to said motor, there being an opening from said chamber, a valve controlling said opening, means on the main slide for closing said valve when the main slide descends relatively to the auxiliary slide.

34. In a machine of the class described, a bottle support, a vertically movable filling head, reciprocable toward and from said bottle support, means for reciprocating said filling head, said filling head having an opening for receiving the head of a bottle and a passage above the same for supplying the bottle with liquid, a rotary disk interposed between said opening and liquid passage, said disk having a liquid opening and a crown receiving opening therein adapted to be brought alternately into registry with the bottle head receiving opening in the filling head and means for moving the disk to bring said openings therein alternately into registry with the bottle receiving opening in the filling head.

35. In a machine of the class described, a filling head having an opening in the lower end thereof, for receiving the head of the bottle, a die above and in registry with said opening, a filling tube extending into said die, means yieldingly holding the filling tube in lowered position, means for supplying liquid to the filling tube, a horizontally movable disk having a liquid passage and an opening to permit the passage of a bottle head therethrough, there being a crown seat at the upper end of said opening, and means for moving the disk to bring the liquid passage and opening alternately in registry with the bottle head receiving opening of the filling head. 70 75 80

36. In a machine of the class described, a bottle support, a filling head vertically reciprocable toward and from said support, said filling head having an opening in the bottom thereof adapted to permit the passage therethrough of the head of a bottle to be filled and crowned, means about said opening for sealing it against the head of a bottle therein, a horizontally movable disk mounted above said opening, having a liquid passage and a passage for the head of a bottle therethrough and a crown seat above the latter passage, said passages being adapted and arranged to be brought alternately into registry with the opening in the filling head, means 90 95 for delivering crowns to the crown seat, a die in the filling head above the disk and in registry with the bottle receiving opening in the filling head, a filling tube extending into the die and means to supply the filling tube with liquid. 100

37. In a machine of the class described, a bottle support, a filling head vertically reciprocable toward and from said support, said filling head having an opening in the bottom thereof adapted to permit the passage therethrough of the head of a bottle to be filled and crowned, a yielding gasket in said opening, means for compressing the gasket vertically to force it into engagement with the head of the bottle therein, a horizontally movable disk mounted above said opening, having a liquid passage and a passage for the head of a bottle therethrough, and a crown seat above the latter passage, said passages being adapted and arranged to be brought alternately into registry with the opening in the filling head, means for delivering crowns to the crown seat, a die in the filling head above the disk and in registry with the bottle head receiving opening in the filling head, a filling tube extending into the die and means to supply the filling tube with liquid. 110 115 120

38. In a machine of the class described, a filling head having a bottle receiving opening in the bottom thereof, an auxiliary slide on which the filling head is mounted, a main slide, means for supplying the filling head with liquid, a cup sliding on the lower end of the filling head, said cup having an opening in 125 130

registry with the opening in the filling head, a sealing sleeve intermediate the cup and filling head, a lever pivotally mounted on the auxiliary slide, links connecting the lever and cup, a lever pivotally mounted on the main slide and engaging the first mentioned lever to operate the latter, and a cam on the auxiliary slide engaging the second said lever, whereby when the main slide moves downwardly relatively to the auxiliary slide, the cup moves upward relatively to the filling head.

39. In a machine of the class described, a filling head, a die in said filling head adapted to receive the lip of a bottle with a crown thereon and force the crown into fixed engagement with the lip, a filling tube, a dial below the die having a filling passage therethrough and a passage adapted to receive the head of a bottle, there being a crown seat above the latter passage, means for placing a bottle crown on said seat and means for operating the dial to bring the two openings therein alternately in registry with the bottle head receiving opening of the filling head.

40. In a machine of the class described, a filling and crowning head having a bottle head receiving opening therein, a die above the bottle head receiving opening, an oscillatory dial intermediate said die and bottle head receiving opening, said dial having a liquid opening and an opening adapted to receive the head of a bottle and a crown seat above the latter, a crown delivery device for delivering crowns to the crown seat, comprising a pusher movable into the filling head through an opening therein, means for reciprocating the pusher and means for locating the crowns in advance of the pusher.

41. In a machine of the class described, a filling and crowning head having a bottle receiving opening in the bottom thereof, means for supplying liquid to be filled to the filling and crowning head, a die therein above and in registry with the bottle head receiving opening in the head, an oscillatory dial intermediate the opening in the filling and crowning head and the die, having a liquid passage and a bottle head receiving passage, means to oscillate the dial to bring the said passages alternately between the opening in the filling head and the die, said means comprising a radially reciprocating block sliding in the dial, a sliding rod extending through the wall of the filling head, a pin on the rod engaging reciprocating block and means exterior to the filling head reciprocating said rod.

42. In a machine of the class described, a filling and crowning head having a bottle receiving opening in the bottom thereof, means for supplying liquid to be filled to the filling and crowning head, a die therein above and in registry with the bottle head receiving opening in the head, an oscillatory

dial intermediate the opening in the filling and crowning head and the die, having a liquid passage and a bottle head receiving passage, means to oscillate the dial to bring the said passages alternately between the opening and filling head and the dial, said means comprising a radially reciprocating block sliding in the dial, a sliding rod extending through the wall of the filling head, a pin on the rod engaging reciprocating blocks, a lever pivoted for horizontal movement, a vertical rod on said lever with which said sliding rod is pivoted and a cam for actuating said lever.

43. In a machine of the class described, a crown delivery mechanism having an inclined crown passage, a vertically reciprocable crowning head, having a lateral opening for the delivery of crowns thereto, said head being movable into and out of registry with the passage of the crown delivery mechanism, a pusher mounted to reciprocate horizontally below said passage, means for reciprocating the pusher and a tumbler pivoted below said passage and movable from a position in which the upper surface thereof is inclined to a position in which said surface is substantially horizontal, the end of said tumbler projecting into the path of the crowning head to be tilted thereby.

44. In a machine of the class described a crown delivery mechanism having an inclined crown passage therein, a vertically reciprocating crowning head having a lateral opening for the delivery of crowns thereto, said head being movable into and out of registry with the passage of the crown delivery mechanism, a pusher mounted to reciprocate horizontally beneath said passage, means for reciprocating the pusher and a tumbler pivoted below said passage and movable from a position in which the upper surface is inclined to a position in which a portion of said surface is substantially horizontal, said tumbler extending into the path of movement of the head to be tilted to the inclined position by the head when the latter descends and means to restore the tumbler to said position in which a portion of the upper surface thereof is substantially horizontal.

45. In a machine of the class described, a crown delivery mechanism having an inclined crown passage therein, a vertically reciprocating crowning head having a lateral opening for the delivery of crowns thereto, said head being movable into and out of registry with the passage in the crown delivery mechanism, a pusher mounted to reciprocate horizontally beneath said passage, means for reciprocating the pusher, a spring pressed dog vertically movable from a position in which it projects into said passage to intercept the crowns therein to a position outside of the said passage, and means op-

erated by the descent of the crowning head to withdraw the dog from the passage.

46. In a machine of the class described, a crown delivery mechanism having an inclined crown passage therein, a vertically reciprocating crowning head having a lateral opening for the delivery of crowns thereto, said head being movable into and out of registry with the passage in the crown delivery mechanism, a pusher mounted to reciprocate horizontally beneath said passage, means for reciprocating the pusher, a spring pressed dog vertically movable from a position in which it projects into said passage to intercept the crowns therein to a position outside of the said passage, means for withdrawing the dog from the passage, and means for returning the dog thereto.

47. In a machine of the class described, a crown delivery mechanism having an inclined crown passage, a vertically reciprocating crowning head having a lateral opening therein for the delivery of crowns thereto, said head being movable to bring said opening into and out of registry with the passage of the crown delivery mechanism, a pusher mounted to reciprocate horizontally beneath said passage, means for reciprocating the pusher, a vertically sliding dog movable from a position in which it extends into said passage to a position outside said passage, a main slide vertically movable in the machine, an auxiliary slide carrying said crowning head and having movement independent of the main slide, a tappet on the main slide pivoted thereto and adapted to engage the dog to raise the same, a cam on the auxiliary slides adapted to swing the tappet when the main slide moves downwardly relatively to the auxiliary slide, and means for reciprocating said slides.

48. In a machine of the class described, a bottle support, a filling head, an auxiliary slide carrying said filling head, a main slide in which said auxiliary slide is mounted, a sealing cup mounted to slide on the lower end of the filling head, there being bottle head receiving openings in said head and cup, an annular compressible seal between the cup and filling head surrounding the openings therein, and means on the slides for moving said cup toward and from the filling head when the main slide moves relatively to the auxiliary slide.

49. In a machine of the class described, a bottle support, a filling head, an auxiliary slide carrying the filling head, a main slide on which the auxiliary slide is mounted for reciprocation, means in the filling head for applying a crown to a bottle, a crown delivery device including a horizontally movable pusher for delivering crowns to the filling head, a cam cylinder revoluble on the vertical axis, means for revolving said cam cylinder, means on the main and auxiliary slide engaging the cam cylinder for reciprocating said

slides, a lever also engaging said cam cylinder and connections between the lever and pusher for operating the latter.

50. In a bottle filling machine, a bottle support, a filling head vertically movable into and out of filling position above said support, a main shaft, a cam on said shaft, connections between said cam and head for reciprocating the latter, means for driving said shaft, a clutch intermediate the shaft and driving means, an arm engaging a member of the clutch for opening the latter, means for swinging the arm to open the clutch when the filling head arrives at the filling position, a tank for receiving carbonated water, connections between the tank and filling head for supplying the latter, a valve in said connection, and connections between said valve and said arm for opening the valve when the filling head is in filling position.

In testimony whereof, I have subscribed my name.

VALENTINE J. MOHLER.
